2-LOWER ALKYL STEROIDAL COMPOUNDS

Mary A. Scheri, Kalamazoo, and Gunther S. Fonken and John A. Hogg, Kalamazoo Township, Kalamazoo County, Mich., assignors to The Upjohn Company, Kalamazoo, Mich., a corporation of Michigan

No Drawing. Application November 16, 1955

Serial No. 547,313

14 Claims. (Cl. 260—397.45)

2

The present invention relates to novel steroids and is more particularly concerned with 2-substituted-3-keto-11-oxygenated-4-pregnanes.

The novel compounds of the present invention and the process of production therefor may be represented by the following sequence of formulae:

wherein R is selected from the group consisting of hydrogen and acyl in which the acyl radical is of an organic carboxylic acid, preferably a hydrocarbon carboxylic acid containing from one to eight carbon atoms, inclusive, R_1 is a lower-alkyl containing from one to eight carbon atoms, M is an alkali metal of atomic weight 6 thru 41 and X is a halogen of atomic weight 33 thru 130.

The process of the instant invention comprises: treating a 21-ester of $11\beta,21$ -dihydroxy-4,17(20)-[trans]-pregnadien-3-one (I) with a lower alkyl ester of oxalic acid in the presence of an alkali metal base to give the corresponding alkali metal enolate of 2-lower-alkyloxy-oxalyl- $11\beta,21$ -dihydroxy-4,17(20)-[trans]-pregnadien-3-one (II). The alkali metal enolate (II) or its 21-esters produced by esterification in conventional manner (with anhydride or halides of organic carboxylic acids, preferably hydrocarbon carboxylic acids containing from one to eight carbon atoms, inclusive) is thereupon treated with a lower-alkyl bromide or iodide to give a 2-lower-alkyloxyoxalyl-2-lower-alkyl- $11\beta,21$ -dihydroxy-4,17(20)-[trans]-pregnadien-3-one or the corresponding 21-ester thereof (III), which is hydrolyzed with an alkali base, such as an alkali alkoxide to give 2-lower-alkyl- $11\beta,21$ -dihydroxy-4,17(20)-[trans]-pregnadien-3-one (IV). Esterification of (IV) is productive of the 21-ester, 2-lower-alkyl- 11β -hydroxy-21-acyloxy-4,17(20)-[trans]-pregnadien-3-one (V). The ester (V) is thereupon treated with osmium tetroxide to give the corresponding intermediate 17,20-osmate which is decomposed with sulfur dioxide gas in water (sulfurous acid) to give 2-lower-alkyl- $11\beta,17\alpha,20\beta,21$ -tetrahydroxy-4-pregn-3-one 21-acylate (VI). Compound (VI) by hydrolysis in a mildly alkali medium (preferably in a nitrogen atmosphere) provides the free tetro, 2-lower-alkyl- $11\beta,17\alpha,20\beta,21$ -tetrahydroxy-4-pregn-3-one which can be esterified in conventional manner to provide the diester, 2-lower-alkyl- $11\beta,17\alpha$ -dihydroxy- $20\beta,21$ -diacyloxy-4-pregn-3-one. Oxidation of this diester with chromic acid produces 2-lower-alkyl- 17α -hydroxy- $20\beta,21$ -diacyloxy-4-pregnene-3,11-dione. Dehydration of 2-lower-alkyl- $11\beta,17\alpha,20\beta,21$ -tetrahydroxy-4-pregnene-3-one $20\beta,21$ -diacylate illustratively with a hypohalous acid and then with anhydrous sulfur dioxide produces 2-lower-alkyl- 17α -hydroxy- $20\beta,21$ -diacyloxy-4,9(11)-pregnadien-3-one (VII). Addition of a hypohalous acid such as hypochlorous or hypobromous acid results in 2-lower-alkyl- 9α -halo- $11\beta,17\alpha$ -dihydroxy-

30 20 β ,21-diacyloxy-4-pregn-3-one (VIII) which by treatment with a base such as anhydrous potassium acetate yields the epoxy compound 2-lower-alkyl-9 β ,11 β -epoxy-17 α -hydroxy-20 β ,21-diacyloxy-4 - pregnen - 3 - one (IX). Treatment of epoxy compound (IX) with hydrogen fluoride or other hydrogen fluoride releasing agents provides the active fluoro derivative, 2-lower-alkyl-9 α -fluoro-11 β ,17 α -dihydroxy-20 β ,21-diacyloxy-4 - pregnen - 3 - one (X). Oxidation of compound (X) with chromic acid in acetic acid provides the 2-lower-alkyl-9 α -fluoro-17 α -40 hydroxy-20 β ,21-dihydroxy-4-pregnene-3,11 - dione (XI). Oxidation of compound VIII in the same manner as compound X results in other 2-lower-alkyl-9 α -halo-17 α -hydroxy-20 β ,21-diacyloxy-4-pregnene-3,11-diones wherein halo is chloro, bromo or iodo. Hydrolysis of the esters 45 provides the free alcohols of these compounds which are useful either per se or as intermediates to produce by re-esterification more desirable esters of the free alcohols, such as 21-monoesters of 2-lower-alkyl-11 β ,17 α ,20 β ,21-tetrahydroxy-4-pregn-3-ones, 2-lower-alkyl-17 α ,20 β ,21-50 trihydroxy-4-pregnene-3,11-diones and their 9 α -halo derivatives.

It is an object of the present invention to produce certain 2 - substituted - 3 - keto - 11 - oxygenated - 4-pregnanes. It is a particular object of the present invention to produce 2 - substituted - 3 - keto - 11 - oxygenated-4-pregnanes selected from the group consisting of alkali metal enolates of 2-lower-alkyloxyoxyl-11 β ,21-dihydroxy - 4,17(20) - pregnadien - 3 - ones, and 2 - lower - alkyloxyoxyl - 11 β - hydroxy - 21 - acyloxy-4,17(20) - pregnadien - 3 ones, 2 - lower - alkyloxyoxyl - 2 - lower - alkyl - 11 β ,21 - dihydroxy - 4,17(20) - pregnadien - 3 one, and 2 - lower - alkyloxy - oxaryl - 2 - lower - alkyl - 11 β - hydroxy - 21 - acyloxy - 4,17(20) - pregnadien - 3 - one, 2 - lower - alkyl - 11 β ,21 - dihydroxy - 4,17(20) - pregnadien - 3 - one, 2 - lower - alkyloxy - 11 β - hydroxy - 21 - acyloxy - 4,17(20) - pregnadien - 3 - one, 2 - lower - alkyl - 11 β ,17 α ,20 β - trihydroxy - 21 - acyloxy - 4 - pregnen - 3 - one, 2 - lower - alkyl - 11 β ,17 α -dihydroxy - 20,21 - diacyloxy - 4 - pregnen - 3 one, 2 - lower - alkyl - 11 β ,17 α ,20,21 - tetrahydroxy - 4 - pregnen - 3 - one, 2 - lower - alkyl - 17 α - hydroxy - 20,21 - diacyloxy - 4 - pregnene - 3,11 - dione, 2 - lower - alkyl - 17 α ,20 β ,21 - trihydroxy - 4 pregnene - 3,11 - dione, 2 - lower - alkyl - 17 α - hydroxy - 20 β ,21 - diacyloxy - 4,9-(11) - pregnadien - 3 one, 2 - lower - alkyl - 17 α ,20 β ,21-

trihydroxy - 4,9(11) - pregnadien - 3 one, 2 - lower-alkyl - 9 α - halo - 11 β ,17 α - dihydroxy - 20 β ,21 - diacyloxy - 4 - pregnen - 3 - one; 2 - lower - alkyl 9 α - halo - 11 β ,17 α ,20 β - trihydroxy - 21 - trimethylacetoxy - 4 - pregnen - 3 one, 2 - lower - alkyl - 9 halo - 11 β ,17 α ,20,21-tetrahydroxy - 4 - pregnen - 3 - one, 2 - lower - alkyl - 9(11) - oxido - 17 α - hydroxy - 20 β ,21 - diacyloxy - 4 - pregnen - 3 - one, 2 - lower - alkyl - 9 α - halo - 17 α - hydroxy - 20 β ,21 - diacyloxy - 4 - pregnen - 3,11 - dione, 2 - lower - alkyl - 9 α - halo - 17 α ,20 β - dihydroxy - 21 - trimethylacetoxy - 4 - pregnen - 3,11 - dione, and 2 - lower - alkyl - 9 α - halo - 17 α ,20,21 - trihydroxy - 4 - pregnen - 3,11-dione wherein the lower-alkyl contains from one to eight carbon atoms, inclusive; the alkali metal is of atomic weight six thru forty, inclusive, the acyl radical is of an organic carboxylic acid, preferably of a hydrocarbon carboxylic acid, containing from one to eight carbon atoms, inclusive, and halo denotes the halogen atoms of atomic weight 17 thru 130, inclusive. It is another object of the instant invention to provide a process for the production of the 2-substituted-3-keto-11-oxygenated-4-pregnenes, especially for the production of 2-alkylated Reichstein's substance E (compound VI) and 2-alkylated Reichstein's substance U, the 20 β ,21-diesters thereof, and the 9 α -halo derivatives (VIII, X, XI) thereof. Other objects will be apparent to those skilled in the art to which this invention pertains.

The compounds of the instant invention are important intermediates in the production of highly active adrenal cortical hormones and in addition possess activity per se. For example, oxidation of 2-lower-alkyl-11 β ,17 α ,20 β -trihydroxy-21-acyloxy-4-pregnene-3-one with manganese dioxide produces the highly active 2-methylhydrocortisone, while similarly oxidation of 2-lower-alkyl-9 α -halo-11 β ,17 α ,20 β -trihydroxy-21-acyloxy-4-pregnene-3-one and hydrolysis produces the extremely active series of 2-alkylated-9 α -halohydrocortisones, of which the 2-methyl-9 α -fluoro-hydrocortisone is one of the most important members. Similarly, oxidation of the corresponding 11-keto analogs, such as 2-lower-alkyl-17 α ,20 β -dihydroxy-21-acyloxy-4-pregnene-3,11-dione and the corresponding 9 α -halo compounds thereof, such as the 2-methyl-9 α -fluoro-17 α ,20 β -dihydroxy-21-acyloxy-4-pregnene-3,11-dione with manganese dioxide provides the corresponding 2-methyl-cortisone respectively 2-methyl-9 α -fluoro cortisone 21-esters. All of these compounds are important adrenal cortical steroids having pronounced cortisone like activity. While the chloro, bromo, and iodo derivatives of these 2-alkylated cortisone and hydrocortisone compounds have activity of considerable significance, the greatest activity has been found in those having in the 9 α -position a fluorine atom. The selective 21-esters possessing a 20 β -free alcohol group are necessary in these oxidations, are either obtained during the process as seen in the example, or are obtained by selective esterification carried out by reacting the selected 2 - alkyl - 11 - oxygenated - 17 α ,20 β ,21 - trihydroxy-4-pregnene-3-one with an acyl halide of a hindered acid such as trimethylacetyl chloride. The 2-methyl-11 β ,17 α ,20,21 - tetrahydroxy - 4 - pregnen - 3 - one per se and the esters thereof as well as the 2-methyl-9 α -fluoro-11 β ,17 α ,20,21-tetrahydroxy-4-pregnene-3-one and the esters thereof have anti-adrenocortical hormonal activity inhibiting, for example, the decrease of adrenal weight by cortisone or hydrocortisone and are therefore usefully administered in prolonged cortisone or hydrocortisone treatment in order to prevent atrophy of the adrenal glands. Similarly the corresponding 11-keto analogs 2-methyl - 17 α ,20 β ,21 - trihydroxy - 4 - pregnen - 3,11-dione and the halo compounds such as 2-methyl-9 α -fluoro-17 α ,20 β ,21 - trihydroxy - 4 - pregnen - 3,11 - dione and esters thereof are useful as anticortical hormonal agents in the same manner as the corresponding 11 β -hydroxy analogs. These compounds also show mineral corticoid activity of a low degree which makes them particularly valuable in combinations with cortisone, hydrocortisone,

or the Δ^1 -cortisone and Δ^1 -hydrocortisone to prevent atrophy of the adrenal glands, as produced by cortisone, hydrocortisone and the Δ^1 -analogs thereof, while not increasing unduly the mineral corticoid activity (salt retention) of the before-mentioned hormones.

The starting materials for the instant process are 11 β ,21 - dihydroxy - 2 - methyl - 4,17(20) - [trans]-pregnadien-3-one 21-acylates such as the 21-acetate, other esters thereof or the free alcohol. 11 β ,21-dihydroxy-4,17(20)-[trans]-pregnadien-3-one and the 21-acetate thereof have been described by Hogg et al., J. Am. Chem. Soc. 77, 4436 (1955). Other 21-esters of 11 β ,21-dihydroxy - 4,17(20) - [trans] - pregnadien - 3 - one are prepared by esterification such as shown in Preparations 1 and 2.

In carrying out the process of the present invention, 11 β ,21-dihydroxy-4,17(20)-[trans]-pregnadien-3-one or a selected 21-ester thereof is admixed with a selected alkali metal condensation catalyst and a dialkyl ester of oxalic acid in an organic solvent. The order of mixing to produce the alkali-metal salt of the compound represented by Formula II is not critical. Reaction solvents which can conveniently be employed in the condensation, include benzene, toluene, xylene, and the like aromatic hydrocarbons, methanol, ethanol, isopropyl alcohol, tertiary butyl alcohol, and other alcohols, tetrahydrofuran, dioxane, diethyl ether, Skellysolve B, hexane hydrocarbons, and other aliphatic hydrocarbons, mixtures of these solvents and other essentially unreactive solvents. Benzene, with or without small percentages of added alkanol, or tertiary butyl alcohol are usually the preferred solvent. The preferred condensation agent is a lower-alkyl oxalic acid ester such as methyl, ethyl, propyl, butyl, pentyl, hexyl, octyl, phenyl, benzyl, or the like oxalic acid esters, with methyl and ethyl oxalate preferred. The condensation is generally conducted at a temperature between about zero degrees centigrade and the boiling point of the reaction mixture. The reaction proceeds with satisfactory rapidity at between about room temperature (twenty to thirty degrees centigrade) and about seventy degrees centigrade, and temperatures substantially above or below this range are therefore not required. The time necessary to obtain substantially complete reaction varies considerably, between about five minutes and several days, depending upon the reaction solvent, the reaction temperature, the selected ester of oxalic acid and the alkali-metal condensation catalyst employed. When methyl or ethyl oxalate and tertiary butyl alcohol are employed at about fifty degrees centigrade, the reaction is usually more than half completed in a few minutes. The condensation step is usually carried out in the absence of any significant amounts of water in any form of the reaction as would be expected in the reaction of this type. To insure the essentially complete exclusion of water from the reaction mixture, the solvent is carefully dried with a drying agent, such as, for example, anhydrous sodium sulfate, calcium sulfate, calcium chloride, phosphorus pentoxide, sodium, or the like, or when an aromatic hydrocarbon is used as a solvent, a portion of the solvent is distilled before using.

Alkali metal condensation catalysts include the alkali metal alkoxides, wherein the alkyl radical of the alkoxy group contains from one to eight carbon atoms, inclusive, and wherein the alkali metal is of atomic weight six thru forty, such as sodium methoxide, sodium ethoxide, sodium isopropoxide, potassium tertiary butoxide, lithium methoxide, and the like, the alkali metals, the alkali metal hydrides, alkali metal amides e. g., sodium amide, and alkyl alkali metals, for example, tiphenylmethyl sodium, and the like. Of these, the alkali metal alkoxides, especially sodium methoxide and sodium ethoxide are preferred for their convenience and consistently satisfactory results. The alkali metal alkoxides may be used solvent-free, dissolved or suspended in a non-reactive solvent, or in situ in the alkanol in which said alkali

metal alkoxide was prepared. When potassium is used, it is usually used as the solution formed by its reaction with tertiary butyl alcohol according to procedures well known in the art. The theoretical alkali metal condensation catalyst required is one mole per mole of steroid. Somewhat more than the theoretical amount is usually employed.

The thus produced alkali metal enolate may be separated by the addition of a large volume of an organic solvent in which the alkali metal enolate is insoluble, such as ether, pentane, or benzene, for example. Another method of producing somewhat purer alkali metal enolate comprises acidification of a cold aqueous solution of the thus precipitated alkali metal enolate to precipitate the free enol and then treating a solution of the free enol in ether or benzene with a chemical equivalent of sodium methoxide, thus reprecipitating the sodium enolate. When the condensation is carried out in the presence of a substantial amount of methyl or ethyl alcohol the removal of said alkali by distillation at reduced pressure before the addition of an additional amount of solvent is preferred, if a high yield of isolated product is to be obtained.

The thus produced alkali metal enolate of 2-lower-alkyl - 11 β ,21 - dihydroxy - 4,17(20) - [trans] - pregnadien-3-one or the corresponding 21-ester thereof is alkylated by the addition of a lower alkyl halide, such as methyl iodide, ethyl iodide, propyl bromide, isopropyl iodide, butyl chloride, bromide and iodide, pentyl chloride, bromide and iodide, hexyl, heptyl, and octyl chloride and bromides, phenyl bromide and iodide, benzyl chloride, bromide or iodide, and the like. In the preferred embodiment the alkyl halide is added to the steroid dissolved in an organic solvent such as methylene chloride, ethylene dichloride, chloroform, carbon tetrachloride, pentanes, hexanes, or the like. After adding the alkyl halide to the solution the reaction is continued for several hours, for example, about eight to about 72 hours at a reaction temperature of about room temperature, twenty to thirty degrees centigrade. Higher temperatures shorten this reaction time considerably. A convenient method of alkylation was the addition of the selected alkyl halide to the reaction product resulting from the condensation step, preferably after the decomposition of any excess alkali metal condensation catalyst. Satisfactory yields are also obtained by stirring the solution of the free active methylene compound, the metal enolate of 2-alkyoxyoxalyl-11 β ,21 - dihydroxy - 4,17(20) - [trans] - pregnadien-3-one or esters thereof with the selected alkyl halide. Alkali metal alkylation catalysts such as sodium or potassium carbonate promote the above reaction, but the reaction is operative without such catalysts. In this manner a 2-lower-alkyoxyoxalyl-2-lower-alkyl-11 β ,21-dihydroxy-4,17(20)-[trans]-pregnadien-3-one is obtained.

The reversal step of the present invention involves the removal of the alkoxyoxalyl group from the 2-position leaving the alkyl group at the 2-position thus producing a 2-lower-alkyl-11 β ,21-dihydroxy-4,17(20)-[trans]-pregnadien-3-one or the respective 21-ester thereof. The reversal step of the present invention is produced by the alkali metal alkylation catalyst, sodium or potassium carbonate, in the presence of water or a lower-alkanol. The reversal reaction is especially promoted by the presence of hydroxide or alkoxide, particularly methoxide and ethoxide ions. After reacting the 2-alkyl-oxo-oxalyl-2 - alkyl - 11 β ,21 - dihydroxy - 4,17(20) - pregnadien-3-one or a 21-ester thereof with a base such as methanol and sodium methoxide, ethanolic methoxide at room temperature, the mixture is poured into a large amount of water and the product is separated by conventional means such as extraction, filtration, or the like, and the material, a 2-alkyl-11 β ,21-dihydroxy-4,17(20)-[trans]-pregnadien-3-one (or a 21-ester thereof), is purified by recrystallization, additional extraction of impurities, chromatography, or the like, as deemed necessary.

The 21-acyloxy group of a 2-lower-alkyoxyoxalyl-2-alkyl-11 β -hydroxy-21-acyloxy - 4,17(20) - [trans] - pregnadien-3-one is removed in the reversal reaction if the acyl group is of a simple unhindered acid such as acetic, propionic, or the like. If the acyl group is of a sterically hindered acid such as dineopentylacetic, trimethylacetic, or the like, the 21-ester group remains intact. In many other cases, a mixture of the ester and the free alcohol is obtained. If desired, the ester is reformed by conventional procedure, such as reacting the obtained 2-lower-alkyl - 11 β ,21 - dihydroxy-4,17(20)-[trans]-pregnadien-3-one with an acid anhydride or acid halide of an organic carboxylic acid, preferably a hydrocarbon carboxylic acid containing from one to eight carbon atoms in pyridine or in a neutral organic solvent such as benzene, toluene, or the like.

The thus obtained 2-lower-alkyl-11 β ,21-dihydroxy-4,17(20)-[trans] - 4 - pregnadien-3-one or the 21-acyloxy esters thereof is hydroxylated with osmium tetroxide and aqueous sulfur dioxide to give the corresponding 2-lower-alkyl-11 β ,17 α ,20 β ,21-tetrahydroxy-4-pregn-3-one. For this purpose the 2 - lower - alkyl - 11 β ,21 - dihydroxy-4,17(20)-[trans]-pregnadien-3-one is dissolved in an organic solvent such as tertiary butyl alcohol, pyridine, diethylether, dioxane, isopropyl alcohol, tetrahydrofuran, tertiary amyl alcohol, ethanol and methanol or the like, with tertiary butyl alcohol preferred, and reacted with the metallic oxide, preferably osmium tetroxide. Other oxides which are operative include manganese dioxide, vanadium pentoxide, chromium trioxide, pertungstic acid, permolybdcic acid, selenium dioxide, and the like. The proportion of osmium tetroxide or other metallic oxide is preferably equal to one mole of metal oxide to one mole of steroid since the hydroxylation reaction requires the intermediate osmate or other peracid ester, however, smaller or larger proportions of the metal oxide are operative. The reaction is carried out at a temperature between minus ten and plus seventy degrees centigrade, preferably at room temperature between fifteen and thirty degrees centigrade. The time of reaction is from several minutes such as five minutes to 24 hours. Long contact of the metal oxides with the steroid produces a high yield in reaction product. The thus obtained ester, illustratively a 17,20-osmate, is hydrolyzed by the addition of water to the ester. If a water miscible solvent such as tertiary butyl alcohol, dioxane, ethyl or methyl alcohol is chosen for the production of the osmate, the addition of water is usually made to the solution containing the osmate ester. If the ester was produced in a solvent immiscible with water, the osmate is separated by evaporating the solvent in vacuo and using without further purification the solid steroid osmate ester. The decomposition of the ester is promoted by adding an acid to the solution, preferably an acid with reductive quality such as sulfuric acid or gaseous sulfur dioxide. The decomposition in the presence of sulfur dioxide or sulfuric acid proceeds rapidly and is usually terminated inside of five to thirty minutes. The thus obtained 11 β ,17 α ,20 β ,21-tetrahydroxy-4-pregn-3-one or 21-acylate is isolated from the reaction mixture by, for example, extraction with a water immiscible solvent such as ether, methylene chloride, chloroform, carbon tetrachloride, benzene, toluene, or the like, and the extracts are evaporated to give the crude 2-lower-alkyl-11 β ,17 α ,20 β ,21-tetrahydroxy-4-pregn-3-one 21-acylate which is purified illustratively by recrystallization or chromatography, as deemed necessary.

Hydrolysis of this material by alkali, preferably in a nitrogen atmosphere, produces the free tetro, 2-lower-alkyl-11 β ,17 α ,20 β ,21-tetrahydroxy - 4 - pregnen - 3 - one. Esterification of the tetro with halides and hydrides of organic carboxylic acids or hydrocarbon carboxylic acids containing from one to eight carbon atoms gives ordinarily the diesters, 2-lower-alkyl - 11 β ,17 α - dihydroxy-20 β ,21-diacyloxy-4-pregn-3-ones. If acid halides or

acid anhydrides of highly hindered acids are used, such as trimethylacetyl chloride, dineopentylacetyl bromide, or the like are used, selective esterification in the 21-position, is obtained. In this manner 2-lower-alkyl-11 β ,17 α ,20 β -trihydroxy-21-acyloxy-4-pregn-3-ones can be produced which are valuable for the further oxidation to the corresponding hydrocortisone 21-esters.

Oxidation of the diester, a 2-lower-alkyl-11 β ,17 α -di-hydroxy-20 β ,21-diacyloxy-4-pregn-3-one with chromic acid is productive of the corresponding 2-lower-alkyl-17 α -hydroxy-20 β ,21-diacyloxy-4-pregnene-3,11-dione.

In order to obtain the corresponding 9- α -halo compounds, the 2-lower-alkyl-11 β ,17 α ,20 β ,21-tetrahydroxy-4-pregn-3-one 20 β ,21-diacylate is dehydrated to the corresponding 2-lower-alkyl-17 α ,20 β ,21-trihydroxy-4-pregn-3-one 20 β ,21-diacylate by methods known in the art, suitable dehydrating agents are for example phosphorus oxychloride, hydrochloric acid, or sulfuric acid in acetic acid, in pyrolysis as shown by U. S. Patents 2,640,838 and 2,640,839. In the preferred embodiment of the present invention the dehydration is effected by reacting the 11 β -hydroxy compound with an N-haloamide or N-haloimide in an organic base and treating the thus produced intermediate 11-hypohalite with dry sulfur dioxide in an organic base. As reagents for the production of an 11-hypohalite, the N-haloamide or N-haloimide are used wherein the halogen has an atomic weight from 34 to 130, inclusive, preferably chlorine or bromine. Examples of such compounds are N-chloroacetamide, N-bromoacetamide, N-chlorosuccinimide, N-bromosuccinimide, N-iodosuccinimide, 3-bromo-5,5-dimethylhydantoin and 1,3-dibromo-5,5-dimethylhydantoin. Ordinarily an amount in excess of a molar equivalent, calculated on the starting 11 β -hydroxy steroid, is employed. The base employed in the production of the 11-hypohalite are tertiary amines wherein the amino nitrogen is a member of an aromatic ring, for example, the pyridines, that is, pyridine, alkyl-pyridines, picoline, lutidine, collidine, conyline, parvuline, or the like, or lower fatty amides such as formamide, methylformamide and dimethylformamide. The base is preferably employed in a large molar excess, calculated on the starting 11 β -hydroxy steroid, for example, ten molar equivalents, and is preferably the sole reaction solvent. The reaction to produce an 11-hypohalite is generally conducted under anhydrous conditions preferably containing less than 0.1 molar equivalent of water calculated per mole of steroid. Large proportions of water decrease the yield. The temperature of the reaction is between minus forty and plus seventy degrees centigrade, the lower limit being determined by the solubility of the reaction and solvents and the upper limit being determined by the amount of side reaction which normally accompanies the reaction involving any halo compounds at higher temperatures. Ordinarily, room temperature (twenty to thirty degrees centigrade) is preferred for convenience and the consistently high yields of the desired product which are obtained at this temperature. A reaction period between five minutes to three hours is usually employed at higher temperatures, above thirty degrees centigrade, short reaction times being sufficient to produce completeness of the reaction.

The thus produced 2-lower-alkyl-11 β ,17 α ,20 β ,21-tetrahydroxy-4-pregn-3-one 11 β -hypohalide 20,21-diacylate is then treated with anhydrous sulfur dioxide in the presence of an organic base as described hereinbefore. The anhydrous sulfur dioxide can be in the form of gaseous or liquid sulfur dioxide or in the form of a material which in situ produces sulfur dioxide, for example, alkali metal hyposulfite. The reaction temperature ranges substantially within minus forty and plus seventy degrees centigrade and preferably room temperature (twenty to thirty degrees centigrade). The thus obtained product a 2-lower-alkyl-17 α ,20 β ,21-trihydroxy-4,9(11)-pregnadien-3-one 20,21-diacylate is isolated by conventional means such as extraction from the reaction mixture after the

reaction mixture has been poured into excess of water. Organic water-immiscible solvents such as ether, chloroform, methylene chloride, carbon tetrachloride, ethyl acetate, benzene, hexanes, or the like, are used for the extraction. The thus obtained extracts are conveniently washed, dried and thereupon evaporated to give the crude 2-lower-alkyl-17 α ,20 β ,21-trihydroxy-4,9(11)-pregnadien-3-one 20 β ,21-diesters which are purified by conventional means such as recrystallization or chromatography, as deemed necessary. The thus obtained 2-lower-alkyl-17 α ,20 β ,21-trihydroxy-4,9(11)-pregnadien-3-one 20 β ,21-diacylate is converted to 2-lower-alkyl-9- α -halo-11 β ,17 α ,20 β ,21-tetrahydroxy-4-pregn-3-one diacylate by adding a hypohalous acid such as hypochlorous or hypobromous acid. The hypohalous acid is usually added by reacting an N-halo acid amide or an N-halo acid imide with an acid to produce the hypohalous acid in situ. In the preferred embodiment of the invention, the steroid, a 2-alkyl-17 α ,20 β ,21-trihydroxy-4,9(11)-pregnadien-3-one or the esters thereof is dissolved in an organic solvent such as methylene chloride, tertiary butyl alcohol, dioxane, tertiary amyl alcohol, or the like, and reacted at room temperature with the hypobromous or hypochlorous acid releasing agent in the presence of an acid. Such hypohalous acid releasing agent include the N-bromoacetamide, the N-chloroacetamide, the N-bromosuccinimide, the N-iodosuccinimide, or the like, in the presence of water and an acid such as perchloric acid, dilute sulfuric acid, or the like. The reaction is usually carried out at room temperature, between fifteen to thirty degrees centigrade, however, lower or higher temperatures are operative for the process. The hypohalous acid releasing agent is generally used in one molar or slightly increased, for example, 25 percent increased amounts compared to mole of steroid. A large excess of the hypohalous acid releasing agent while operative is undesirable since the excess of hypohalous acid has a tendency to react on other positions of the molecule. The reaction period is rather short and may vary between about four to five minutes to one hour. At the end of the reaction time excess of hypohalous acid is destroyed by the addition of sodium sulfite or other sulfites or hydrosulfites. The thus produced product, a 2-lower-alkyl-9- α -halo-11 β ,17 α ,20 β ,21-tetrahydroxy-4-pregn-3-one 20,21-diacylate, wherein halo is of atomic weight between 33 and 130, is isolated from the reaction mixture by adding excess of water and extracting the compound with organic solvents or by recovering the precipitated compound through filtration. A crude product thus obtained may be recrystallized from acetone and Skellysolve B hexane hydrocarbons to give pure 2-lower-alkyl-9- α -halo-11 β ,17 α ,20 β ,21-tetrahydroxy-4-pregn-3-ones 20,21-diacylate.

As shown before the diester thus obtained can be hydrolyzed to give the free tetrol, 2-lower-alkyl-9- α -halo-11 β ,17 α ,20 β ,21-tetrahydroxy-4-pregn-3-one, which can be reesterified to give mono or diesters depending on the type and quantity of acylating agent used. Thus, using anhydrides or halides of hydrocarbon carboxylic acids of straight chain structure in excess produces diesters, 2-lower-alkyl-9- α -halo-11 β ,17 α ,20 β ,21-tetrahydroxy-4-pregn-3-one 20 β ,21-diacylates. If halides of sterically hindered acids are used, such as trimethylacetate, triethylacetate, dineopentylacetate, or the like, the corresponding 21-monoesters of 2-lower-alkyl-9- α -halo-11 β ,17 α ,20 β ,21-tetrahydroxy-4-pregn-3-ones are obtained.

Oxidizing the 20,21-diester of a 2-lower-alkyl-11 β ,17 α ,20 β ,21-tetrahydroxy-4-pregn-3-one, with chromic acid produces the corresponding pharmaceutically active 2-lower-alkyl-9- α -halo-17 α ,20 β ,21-trihydroxy-4-pregn-3-11-dione 20 β ,21-diacylate which by hydrolysis gives the free tetrol, 2-lower-alkyl-9- α -halo-11 β ,17 α ,20 β ,21-tetrahydroxy-4-pregn-3,11-dione.

In order to obtain the 9- α -fluoro compounds the 9 β ,11 β -epoxy intermediates of the before-mentioned compounds,

2-lower-alkyl-9 β ,11 β -epoxy - 17 α ,20 β ,21 - trihydroxy - 4 - pregnen-3-one diesters, are prepared. In carrying out this reaction a 2-lower-alkyl-9 α -halo-11 β ,17 α ,20 β ,21-tetrahydroxy-4-pregnen-3-one diester is heated in solution with a mild base, and preferably in the absence of water to avoid hydrolysis of the ester groups.

The bases useful for the cyclization include anhydrous potassium acetate, sodium bicarbonate, sodium acetate, or the like, with potassium acetate preferred. Solvents such as methanol, ethanol, acetone, tertiary butyl alcohol, or the like, may be used. The reaction time is between one half hour and 24 hours; generally a period between three and twelve hours is sufficient. The thus obtained 2-lower-alkyl-9 β ,11 β -epoxy - 17 α ,20 β ,21 - trihydroxy - 4 - pregnen-3-one is isolated from the reaction mixture by pouring the reaction mixture into excess water and extracting with methylene chloride or other water-immiscible solvents such as ether, Skellysolve B hexanes, pentanes, benzene, ethyl acetate, chloroform, carbon tetrachloride, or the like. Evaporation of the solvent of the extracts produces the 2-lower-alkyl-9 β ,11 β -epoxy-17 α ,20 β ,21-trihydroxy-4-pregnen-3-one 20 β ,21-diacylate.

The thus obtained 2-lower-alkyl-9 β ,11 β -epoxy-17 α ,20 β ,21-trihydroxy-4-pregnen-3-one 20 β ,21-diacylate is therupon reacted with 48 percent hydrofluoric acid in solution in the presence of a strong acid. As solvents for this reaction methylene chloride, ethylene dichloride, chloroform, carbon tetrachloride or the like is useful, with methylene chloride preferred. As acid catalysts, perchloric acid, toluene-sulfonic acid, sulfuric acid or the like may be used. The reaction is carried out at room temperature (twenty to thirty degrees centigrade) preferably with stirring. The period of reaction is from one to 24 hours with a period from one to twelve hours usually sufficient. After the reaction is terminated, the mixture is poured into water and neutralized with a dilute base such as sodium bicarbonate, potassium bicarbonate, or the like. Excess of strong bases can also be used. The reaction mixture is then extracted with a water-immiscible solvent such as methylene chloride, the organic layer is separated from the water mixture, washed with water, dried and evaporated to give the crude 2-lower-alkyl-9 α -fluoro - 11 β ,17 α ,20 β ,21 - tetrahydroxy - 4 - pregnen-3-one 20 β ,21-diacylate. The thus obtained crude compound may be purified through recrystallization or chromatography as deemed necessary.

The 2-lower-alkyl - 9 α -fluoro-11 β ,17 α ,20 β ,21-tetrahydroxy-4-pregnen-3-one esters obtained by this process can be hydrolyzed to give the 2-lower-alkyl-9 α -fluoro-11 β ,17 α ,20 β ,21-tetrahydroxy-4-pregnen-3-one which can be selectively esterified with acyl halides of hindered acids, illustratively, trimethylacetyl chloride or dineopentylacetyl chloride in pyridine solution at room temperature to give the corresponding 21-esters of 2-lower-alkyl-9 α -fluoro-11 β ,17 α ,20 β ,21-tetrahydroxy - 4 - pregnen-3-one. Oxidation of the thus obtained 2-lower-alkyl-9 α -fluoro-11 β ,17 α ,20 β ,21-tetrahydroxy - 4 - pregnen-3-one 21-acylate with manganese dioxide produces the corresponding 2-lower-alkyl-9 α -fluorohydrocortisone 21-acylate.

Oxidation of the 2-lower-alkyl-9 α -fluoro-11 β ,17 α ,20 β ,21-tetrahydroxy-4-pregnen - 3 - one 20 β ,21-diacylate with chromic acid produces the corresponding 2-lower-alkyl-9 α -fluoro-17 α ,20 β ,21-trihydroxy - 4 - pregnen-3,11-dione 20 β ,21-diacylate which can be hydrolyzed with sodium bicarbonate in ethanol in a nitrogen atmosphere to give the free triol, 2-lower-alkyl-9 α -fluoro-17 α ,20 β ,21-trihydroxy-4-pregnene-3,11-dione.

The following examples are illustrated for the process and products of the present invention, but are not to be construed as limiting.

PREPARATION 1

11 β ,21-dihydroxy-4,17(20)-[trans]-pregnadien-3-one 21-propionate

5 One gram of 11 β ,21-dihydroxy-4,17(20)-[trans]-pregnadien-3-one was dissolved in ten milliliters of pyridine and ten milliliters of propionic anhydride. The mixture was allowed to stand at room temperature (about 22 to 25 degrees centigrade) overnight (sixteen hours) and thereupon poured into 100 milliliters of ice water. The thus precipitated 11 β ,21 - dihydroxy - 4,17(20) - [trans]-pregnadien-3-one 21-propionate was collected on filter paper and recrystallized from acetone Skellysolve B hexanes to give pure 11 β ,21-dihydroxy-4,17(20)-pregnadien-3-one 21-propionate.

PREPARATION 2

11 β ,21-dihydroxy-4,17(20)-[trans]-pregnadien-3-one 21-benzoate

20 0.5 grams of 11 β ,21-dihydroxy-4,17(20)-[trans]-pregnadien-3-one was dissolved in five milliliters of pyridine and thereto was added three milliliters of benzoyl chloride. The mixture was maintained for a period of eighteen hours and thereupon poured into ice water. The water solution was extracted with three 25-milliliter portions of methylene chloride which thereafter were evaporated in vacuo and the solid material recrystallized from methyl alcohol to give pure 11 β ,21-dihydroxy-4,17(20)-[trans]-pregnadien-3-one 21-benzoate.

25 In the same manner as shown in Preparations 1 and 2, other 21-organic carboxylic acid esters preferably hydrocarbon carboxylic acid esters containing from one to eight carbon atoms of 11 β ,21-dihydroxy-4,17(20)-[trans]-pregnadien-3-one are produced by reacting the steroid compound with an acid halide or acid anhydride in a basic or neutral solvent such as pyridine, toluene, benzene, ether, or the like, to give the corresponding 11 β ,21-dihydroxy-4,17(20)-[trans]-pregnadien - 3 - one 21-acylate comprising the butyrate, isobutyrate, valerate, isovalerate, hexanoate, heptanoate, octanoate, β -cyclopentylpropionate, toluate, gallate, salicylate, anisate, nicotinate, piperonate, benzenepropionate, chloroacetate, dichloroacetate, trichloroacetate, bromoacetate, iodoacetate, fluoroacetate, trifluoroacetate, benzenesulfonate, toluenesulfonate, chlorobenzenesulfonate, para-nitrobenzenesulfonate, nicotinate, piperonate, 2-furoate, trimethylacetate, dineopentyl acetate, acrylate, crotonate, cinnamate, lactate, acid titrate, acid succinate, dihydrogencitrate, or the like.

EXAMPLE 1

Sodium enolate of 2-ethoxyoxalyl-11 β ,21-dihydroxy-4,17(20)-[trans]-pregnadien-3-one 21-acetate

55 A solution of 21 grams of 11 β ,21-dihydroxy-4,17(20)-[trans]-pregnadien-3-one 21-acetate was dissolved in 400 milliliters of tertiary butyl alcohol and heated to seventy degrees centigrade. To this solution was added 16.6 grams of ethyl oxalate and the solution was stirred in an atmosphere of nitrogen for a period of five minutes. Thereafter 9.2 grams of sodium methoxide (37 grams of a 25 percent solution in methanol) was added. The mixture was cooled to 55 degrees centigrade and stirred for a period of thirty minutes. Thereafter 300 milliliters of ether was added and stirring was continued at 25 degrees centigrade for an additional period of thirty minutes. The thus precipitated sodium enolate of 2-ethoxyoxalyl-11 β ,21-dihydroxy - 4,17(20)-[trans]-pregnadien-3-one 21-acetate (2-ethoxyoxalyl - 11 β - hydroxy-21-acetoxy-4,17(20) - [trans] - pregnadien-3-one) was recovered by filtration, the precipitate was washed with 200 milliliters of ether and then dried in vacuo at sixty degrees centigrade for a period of one and one half hours. Infrared spectrum in chloroform were in agreement with the postulated structure for 2-ethoxyoxalyl-

11 β ,21-dihydroxy-4,17(20)-[trans]-pregnadien-3-one 21-acetate.

EXAMPLE 2

(a) Refluxing 11 β ,21-dihydroxy-4,17(20)-[trans]-pregnadien-3-one 21-propionate, dissolved in tertiary butyl alcohol, with methyloxalate in the presence of sodium methoxide produced the sodium enolate of 2-methoxyoxalyl-11 β ,21-dihydroxy-4,17(20)-[trans]-pregnadien-3-one 21-propionate.

(b) Treating 11 β ,21-dihydroxy-4,17(20)-[trans]-pregnadien-3-one 21-benzoate, dissolved in tertiary butyl alcohol, with ethyl oxalate in potassium ethoxide produced the potassium enolate of 2-ethoxyoxalyl-11 β ,21-dihydroxy-4,17(20)-[trans]-pregnadien-3-one 21-benzoate.

(c) Treating 11 β ,21-dihydroxy-4,17(20)-[trans]-pregnadien-3-one 21-phenylacetate dissolved in tertiary butyl alcohol with butyl oxalate in the presence of lithium butoxide yielded the lithium enolate of 2-butoxyoxalyl-11 β ,21-dihydroxy-4,17(20)-[trans]-pregnadien-3-one 21-phenylacetate.

(d) Reacting 11 β ,21-dihydroxy-4,17(20)-[trans]-pregnadien-3-one 21-trimethylacetate with ethyl oxalate in the presence of potassium ethoxide yielded a potassium enolate of 2-ethoxyoxalyl-11 β ,21-dihydroxy-4,17(20)-[trans]-pregnadien-3-one 21-trimethylacetate.

(e) Treating 11 β ,21-dihydroxy-4,17(20)-[trans]-pregnadien-3-one with potassium ethoxide and methyl oxalate produced the potassium enolate of 2-methoxyoxalyl-11 β ,21-dihydroxy-4,17(20)-[trans]-pregnadien-3-one.

In the same manner as shown in Examples 1 and 2 treating other 21-esters of 11 β ,21-dihydroxy-4,17(20)-[trans]-pregnadien-3-one with a lower-alkyl oxalate in the presence of a base such as sodium, potassium, lithium, methoxide, ethoxide, propoxide, butoxide, or the like, produces the corresponding alkali metal enolates of the 2-lower-alkyl-11 β ,21-dihydroxy-4,17(20)-[trans]-pregnadien-3-one 21-acylates. Such produced alkali metal enolates of 2-alkoxyoxalyl-11 β ,21-dihydroxy-4,17(20)-[trans]-pregnadien-3-one 21-acylates comprise: the sodium, potassium and lithium enolate of 2-butoxyoxalyl-11 β ,21-dihydroxy-4,17(20)-[trans]-pregnadien-3-one 21-acetate, 2-amyloxyoxalyl-11 β ,21-dihydroxy-4,17(20)-[trans]-pregnadien-3-one 21-acetate, 2-hexyloxyoxalyl-11 β ,21-dihydroxy-4,17(20)-[trans]-pregnadien-3-one 21-acetate, 2-heptyloxyoxalyl-11 β ,21-dihydroxy-4,17(20)-[trans]-pregnadien-3-one 21-acetate, 2-octyloxyoxalyl-11 β ,21-dihydroxy-4,17(20)-[trans]-pregnadien-3-one 21-acetate; the sodium, potassium and lithium enolates of 2-methoxyoxalyl and 2-ethoxyoxalyl-11 β ,21-dihydroxy-4,17(20)-[trans]-pregnadien-3-one 21-acylates wherein the acylate group is valerate, isovalerate, hexanoate, heptanoate, octanoate, β -cyclopentylpropionate, phenylpropionate, anisate, diisopentylacetate, triethylacetate, salicylate, toluate, acid succinate, acid tartrate, acid maleate, chlороacetate, dichloroacetate, trichloroacetate, bromoacetate, iodoacetate, fluoroacetate, trifluoroacetate, ortho-bromobenzoate, meta-nitrobenzoate, toluenesulfonate, benzenesulfonate, or the like.

EXAMPLE 3

2-ethoxyoxalyl-2-methyl-11 β ,21-dihydroxy-4,17(20)-[trans]-pregnadien-3-one 21-acetate

A mixture of 32 grams of the sodium enolate of 2-ethoxyoxalyl-11 β ,21-dihydroxy-4,17(20)-[trans]-pregnadien-3-one 21-acetate, 35 grams of potassium carbonate and seventy milliliters of methyl iodide, dissolved in one liter of acetone, were refluxed for a period of eighteen hours. The mixture was then concentrated to about 750 milliliters of volume, cooled and filtered. The potassium carbonate filter cake was washed with four 250-milliliter portions of hot acetone. The combined acetone solution was distilled to dryness at reduced pressure to give 2-ethoxyoxalyl-2-methyl-11 β ,21-dihydroxy-

4,17(20)-[trans]-pregnadien-3-one 21-acetate (2-ethoxyoxalyl-2-methyl-11 β -hydroxy-21-acetoxy-4,17(20)-[trans]-pregnadien-3-one). The infrared spectrum of 2-ethoxyoxalyl-2-methyl-11 β ,21-dihydroxy-4,17(20)-[trans]-pregnadien-3-one 21-acetate in chloroform corresponded to the proposed structure.

EXAMPLE 4

In the manner shown in Example 3,

(a) Treating the sodium enolate of 2-ethoxyoxalyl-11 β ,21-dihydroxy-4,17(20)-[trans]-pregnadien-3-one 21-propionate with methyl iodide in the presence of sodium carbonate produced 2-ethoxyoxalyl-2-methyl-11 β ,21-dihydroxy-4,17(20)-[trans]-pregnadien-3-one 21-propionate.

(b) Treating the potassium enolate of 2-methoxyoxalyl-11 β ,21-dihydroxy-4,17(20)-[trans]-pregnadien-3-one 21-benzoate with methyl iodide in the presence of sodium carbonate produced 2-methoxyoxalyl-2-methyl-11 β ,21-dihydroxy-4,17(20)-[trans]-pregnadien-3-one 21-benzoate.

(c) Treating the potassium enolate of 2-ethoxyoxalyl-11 β ,21-dihydroxy-4,17(20)-[trans]-pregnadien-3-one 21-phenylacetate with methyl iodide in the presence of sodium carbonate produced 2-ethoxyoxalyl-2-methyl-11 β ,21-dihydroxy-4,17(20)-[trans]-pregnadien-3-one 21-phenylacetate.

(d) Treating the lithium enolate of 2-butoxyoxalyl-11 β ,21-dihydroxy-4,17(20)-[trans]-pregnadien-3-one 21-acetate with methyl iodide in the presence of sodium carbonate produced 2-butoxyoxalyl-2-methyl-11 β ,21-dihydroxy-4,17(20)-[trans]-pregnadien-3-one 21-acetate.

(e) Treating the sodium enolate of 2-ethoxyoxalyl-11 β ,21-dihydroxy-4,17(20)-[trans]-pregnadien-3-one 21 with butyl bromide in the presence of potassium carbonate produced 2-ethoxyoxalyl-2-butyl-11 β ,21-dihydroxy-4,17(20)-[trans]-pregnadien-3-one.

(f) Treating the sodium enolate of 2-ethoxyoxalyl-11 β ,21-dihydroxy-4,17(20)-[trans]-pregnadien-3-one 21-acetate with ethyl iodide in the presence of potassium carbonate produced 2-ethoxyoxalyl-2-ethyl-11 β ,21-dihydroxy-4,17(20)-[trans]-pregnadien-3-one 21-acetate.

(g) Treating the sodium enolate of 2-ethoxyoxalyl-11 β ,21-dihydroxy-4,17(20)-[trans]-pregnadien-3-one 21-acetate with propyl iodide in the presence of potassium carbonate produced 2-ethoxyoxalyl-2-propyl-11 β ,21-dihydroxy-4,17(20)-[trans]-pregnadien-3-one 21-acetate.

(h) Treating the sodium enolate of 2-ethoxyoxalyl-11 β ,21-dihydroxy-4,17(20)-[trans]-pregnadien-3-one 21-acetate with pentyl iodide in the presence of potassium carbonate produced 2-ethoxyoxalyl-2-pentyl-11 β ,21-dihydroxy-4,17(20)-[trans]-pregnadien-3-one 21-acetate.

(i) Treating the sodium enolate of 2-ethoxyoxalyl-11 β ,21-dihydroxy-4,17(20)-[trans]-pregnadien-3-one 21-acetate with hexyl chloride in the presence of potassium carbonate produced 2-ethoxyoxalyl-2-hexyl-11 β ,21-dihydroxy-4,17(20)-[trans]-pregnadien-3-one 21-acetate.

(j) Treating the sodium enolate of 2-ethoxyoxalyl-11 β ,21-dihydroxy-4,17(20)-[trans]-pregnadien-3-one 21-acetate with heptyl iodide in the presence of potassium carbonate produced 2-ethoxyoxalyl-2-heptyl-11 β ,21-dihydroxy-4,17(20)-[trans]-pregnadien-3-one 21-acetate.

(k) Treating the sodium enolate of 2-ethoxyoxalyl-11 β ,21-dihydroxy-4,17(20)-[trans]-pregnadien-3-one 21-acetate with octyl iodide in the presence of potassium carbonate produced 2-ethoxyoxalyl-2-octyl-11 β ,21-dihydroxy-4,17(20)-[trans]-pregnadien-3-one 21-acetate.

(l) Treating the sodium enolate of 2-ethoxyoxalyl-11 β ,21-dihydroxy-4,17(20)-[trans]-pregnadien-3-one 21-acetate with benzyl iodide in the presence of potassium carbonate produced 2-ethoxyoxalyl-2-benzyl-11 β ,21-dihydroxy-4,17(20)-[trans]-pregnadien-3-one 21-acetate.

(m) Treating the sodium enolate of 2-ethoxyoxalyl-11 β ,21-dihydroxy-4,17(20)-[trans]-pregnadien-3-one 21-acetate with phenyl iodide in the presence of potassium

15

carbonate produced 2-ethoxyoxaryl-2-phenyl-11 β ,21-dihydroxy-4,17(20)-[trans]-pregnadien-3-one 21-acetate.

In the same manner as shown in Examples 3 and 4, treating an alkali metal enolate of a 2-lower-alkyloxaryl-11 β ,21-dihydroxy-4,17(20)-[trans]-pregnadien-3-one 21-acylates with a lower-alkyl halide preferably a lower-alkyl halide wherein the alkyl group has from one to eight carbon atoms and the halogen an atomic weight between 34 and 130 preferably in the presence of a catalyst such as sodium or potassium carbonate produces the corresponding 2-lower-alkyloxaryl-2-alkyl-11 β ,21-dihydroxy-4,17(20)-[trans]-pregnadien-3-one 21-acylates illustratively those 2-lower-alkyloxaryl-2-alkyl-11 β ,21-dihydroxy-4,17(20)-[trans]-pregnadien-3-one 21-acylates wherein the alkoxy group is methoxy, ethoxy, propoxy, butoxy, pentoxy, hexoxy, heptoxy, octoxy, or the like, the alkyl group is methyl, ethyl, propyl, pentyl, hexyl, heptyl, octyl, benzyl, phenyl, or the like, and the acyl group of the acylate is acetyl, propionyl, butyryl, valeryl, isovaleryl, hexanoyl, heptanoyl, octanoyl, benzoyl, toluenesulfonyl, anisoyl, gallyl, toluyl, chloroacetyl, dichloroacetyl, or the like.

EXAMPLE 5

2-methyl-11 β ,21-dihydroxy-4,17(20)-[trans]-pregnadien-3-one 21-acetate

Thirty grams of 2-ethoxyoxaryl-2-methyl-11 β ,21-dihydroxy-4,17(20)-[trans]-pregnadien-3-one 21-acetate was dissolved in 350 milliliters of methanol and thereto was added eighteen milliliters of sodium methoxide solution (25 percent solution of sodium methoxide in methanol). The reaction mixture thus obtained was stirred for a period of five hours and then allowed to stand overnight (eighteen hours) at room temperature (22 to 25 degrees centigrade). At the end of this period, the solution was extracted with five 200-milliliter portions of methylene chloride. The combined extracts were washed once with water and once with saturated aqueous sodium chloride solution, filtered through anhydrous sodium sulfate and concentrated to dryness at reduced pressure. The residue thus obtained was 2-methyl-11 β ,21-dihydroxy-4,17(20)-[trans]-pregnadien-3-one.

The thus obtained 2-methyl-11 β ,21-dihydroxy-4,17(20)-[trans]-pregnadien-3-one was dissolved in seventy milliliters of pyridine and thereto was added 100 milliliters of acetic anhydride. The mixture was maintained at room temperature, about 22 to 25 degrees centigrade, for a period of eighteen hours. Thereafter the mixture was poured into ice water and extracted with methylene chloride. The methylene chloride extracts were dried over anhydrous sodium sulfate, concentrated to dryness at reduced pressure and the remaining crude residue was chromatographed over 1140 grams of Florisil magnesium silicate. Fractions of 1000 milliliters were taken as follows:

TABLE I

Fraction No.	Solvent
1-14	Skellysolve B hexane:acetone 9:1.
15-20	Skellysolve B hexane:acetone 3:1.
21-24	Acetone.

Fractions 4-8 were combined and evaporated. The thus obtained crystalline material was recrystallized from ethyl acetate-Skellysolve B hexane to give 2.47 grams of 2-methyl-11 β ,21-dihydroxy-4,17(20)-[trans]-pregnadien-3-one 21-acetate (2-methyl-11 β -hydroxy-21-acetoxy-4,17(20)-[trans]-pregnadien-3-one) of melting point 163 to 171 degrees centigrade, $[\alpha]_D$ (acetone) plus 128 degrees.

Analysis.—Calcd. for $C_{24}H_{34}O_4$: C, 74.57; H, 8.87. Found: C, 74.27; H, 9.27.

16

EXAMPLE 6

2-methyl-11 β ,21-dihydroxy-4,17(20)-[trans]-pregnadien-3-one

In the manner shown in Example 5, treating 2-ethoxyoxaryl-2-methyl-11 β ,21-dihydroxy-4,17(20)-[trans]-pregnadien-3-one 21-propionate with potassium ethoxide in ethanol solution resulted in 2-methyl-11 β ,21-dihydroxy-4,17(20)-[trans]-pregnadien-3-one.

Hydrolyzing in the manner shown in Examples 5 and 6, the 2-methoxyoxaryl-2-methyl-11 β ,21-dihydroxy-4,17(20)-[trans]-pregnadien-3-one 21-benzoate of Example 4b, 2-ethoxyoxaryl-2-methyl-11 β ,21-dihydroxy-4,17(20)-[trans]-pregnadien-3-one 21-phenylacetate of Example 4c, and the 2-butoxyoxaryl-2-methyl-11 β ,21-dihydroxy-4,17(20)-[trans]-pregnadien-3-one 21-acetate of Example 4d, with sodium ethoxide or sodium methoxide in methanol or ethanol solution or with other bases such as sodium carbonate, sodium bicarbonate, potassium carbonate, or the like in aqueous alcoholic solution yielded 2-methyl-11 β ,21-dihydroxy-4,17(20)-[trans]-pregnadien-3-one.

EXAMPLE 7

Hydrolyzing in the manner shown in Example 5 with potassium methoxide in ethanol:

(a) 2-ethoxyoxaryl-2-butyl-11 β ,21-dihydroxy-4,17(20)-[trans]-pregnadien-3-one yielded 2-butyl-11 β ,21-dihydroxy-4,17(20)-[trans]-pregnadien-3-one.

(b) 2-ethoxyoxaryl-2-ethyl-11 β ,21-dihydroxy-4,17(20)-[trans]-pregnadien-3-one 21-acetate yielded 2-ethyl-11 β ,21-dihydroxy-4,17(20)-[trans]-pregnadien-3-one;

(c) 2-ethoxyoxaryl-2-propyl-11 β ,21-dihydroxy-4,17(20)-[trans]-pregnadien-3-one yielded 2-propyl-11 β ,21-dihydroxy-4,17(20)-[trans]-pregnadien-3-one.

(d) 2-ethoxyoxaryl-2-pentyl-11 β ,21-dihydroxy-4,17(20)-[trans]-pregnadien-3-one 21-acetate yielded 2-pentyl-11 β ,21-dihydroxy-4,17(20)-[trans]-pregnadien-3-one.

(e) 2-ethoxyoxaryl-2-hexyl-11 β ,21-dihydroxy-4,17(20)-[trans]-pregnadien-3-one 21-acetate yielded 2-hexyl-11 β ,21-dihydroxy-4,17(20)-[trans]-pregnadien-3-one.

(f) 2-ethoxyoxaryl-2-heptyl-11 β ,21-dihydroxy-4,17(20)-[trans]-pregnadien-3-one 21-acetate yielded 2-heptyl-11 β ,21-dihydroxy-4,17(20)-[trans]-pregnadien-3-one.

(g) 2-ethoxyoxaryl-2-octyl-11 β ,21-dihydroxy-4,17(20)-[trans]-pregnadien-3-one 21-acetate yielded 2-octyl-11 β ,21-dihydroxy-4,17(20)-[trans]-pregnadien-3-one.

(h) 2-ethoxyoxaryl-2-benzyl-11 β ,21-dihydroxy-4,17(20)-[trans]-pregnadien-3-one 21-acetate yielded 2-benzyl-11 β ,21-dihydroxy-4,17(20)-[trans]-pregnadien-3-one.

(i) 2-ethoxyoxaryl-2-phenyl-11 β ,21-dihydroxy-4,17(20)-[trans]-pregnadien-3-one 21-acetate yielded 2-phenyl-11 β ,21-dihydroxy-4,17(20)-[trans]-pregnadien-3-one.

In the same manner as shown in Example 5, the 21-alcohols of 2-lower-alkyl-11 β ,21-dihydroxy-4,17(20)-[trans]-pregnadien-3-one of Examples 5, 6, and 7 can be esterified to give the corresponding 21-esters. Esterification is usually carried out in the manner shown

in Example 5, using a solvent such as pyridine or a neutral solvent such as ether, benzene, toluene, or the like, and an esterification reagent such as an anhydride or a chloride or bromide of an organic carboxylic acid respectively of a hydrocarbon carboxylic acid. The anhydrides and halides of organic carboxylic acids or hydrocarbon carboxylic acids useful in the esterification comprise those from one to eight carbon atoms in particular, but those containing up to twelve carbon atoms such as, for example, lauryl or dineopentylacetyl bromide or chloride are utilizable. The thus obtained 2-lower-alkyl-11 β ,

dihydroxy - 4,17(20) - [trans] - pregnadien - 3 - ones 21-acylates comprise the 21-acetate, propionate, cyclopentylpropionate, butyrate, isobutyrate, valerate, isovalerate, hexanoate, heptanoate, octanoate, phenylacetate, benzoate, toluate, trimethylacetate, dienepentylacetate, triethylacetate, a chloro, bromo and iodo and fluoroacetate, trichloro- and trifluoroacetate, toluenesulfonate, benzenesulfonate, nictonate, 2-furoate, and other acid esters of 2-lower-alkyl-11 β ,21-dihydroxy-4,17(20)-[trans]-pregnadien-3-one wherein the lower-alkyl group comprises methyl, ethyl, propyl, isopropyl, butyl, isobutyl, pentyl, hexyl, octyl, phenyl, benzyl, or the like.

EXAMPLE 8

2 - methyl - 11 β ,17 α ,20 β ,21 - tetrahydroxy - 4 - pregnen-3-one 21-acetate (2-methyl-11 β ,17 α ,20 β -trihydroxy-21-acetoxy-4-pregn-3-one)

A solution was prepared containing 2.47 grams of 2-methyl - 11 β ,21 - dihydroxy - 4,17(20) - [trans] - pregnadien-3-one 21-acetate, dissolved in 100 milliliters of tertiarybutyl alcohol, fifteen milliliters of pyridine and 1.78 grams of osmium tetroxide. The solution was stirred at room temperature at about 23 degrees centigrade for thirty minutes and then allowed to stand overnight at room temperature (22 to 25 degrees centigrade). To this solution was then added 100 milliliters of water. Thereupon sulfur dioxide gas was bubbled through the mixture for a period of ten minutes. Thereafter an additional 100 milliliters of water were added and the solution was extracted with 250 milliliters of methylene chloride. The methylene chloride extracts were washed, once with water, once with four percent aqueous sodium bicarbonate, filtered through anhydrous sodium sulfate and concentrated to dryness at reduced pressure. The thus obtained product was recrystallized from ethyl acetate-Skellysolve B hexanes to give pure 2-methyl-11 β ,17 α ,20 β ,31-tetrahydroxy-4-pregn-3-one 21-acetate (2-methyl Reichstein's substance E 21-acetate) of melting point 199 to 203 and rotation $[\alpha]_D$ of plus 120 degrees (acetone).

Analysis.—Calcd. for C₂₄H₃₆O₆: C, 68.54; H, 8.63. Found: C, 68.44; H, 8.69.

EXAMPLE 9

In the same manner as shown in Example 8, treating with osmium tetroxide in tertiary butyl alcohol and pyridine:

(a) 2 - methyl - 11 β ,21 - dihydroxy - 4,17(20) - [trans]-pregnadien-3-one and hydrolyzing the thus produced 17(20)-osmate with water and sulfur dioxide yielded 2 - methyl - 11 β ,17 α ,20 β ,21 - tetrahydroxy - 4-pregn-3-one.

(b) 2 - ethyl - 11 β ,21 - dihydroxy - 4,17(20) - [trans]-pregnadien-3-one 21-acetate and hydrolyzing the thus produced 17(20)-osmate with water and sulfur dioxide yielded 2 - ethyl - 11 β ,17 α ,20 β ,21 - tetrahydroxy - 4-pregn-3-one 21-acetate.

(c) 2 - propyl - 11 β ,21 - dihydroxy-4,17(20)-[trans]-pregnadien-3-one 21-acetate and hydrolyzing the thus produced 17(20)-osmate with water and sulfur dioxide yielded 2 - propyl - 11 β ,17 α ,20 β ,21 - tetrahydroxy - 4-pregn-3-one 21-acetate.

(d) 2 - isopropyl - 11 β ,21 - dihydroxy - 4,17(20) - [trans]-pregnadien-3-one 21-acetate and hydrolyzing the thus produced 17(20)-osmate with water and sulfur dioxide yielded 2-isopropyl-11 β ,17 α ,20 β ,21-tetrahydroxy-4-pregn-3-one 21-acetate.

(e) 2 - butyl - 11 β ,21 - dihydroxy - 4,17(20) - [trans]-pregnadien-3-one 21-acetate and hydrolyzing the thus produced 17(20)-osmate with water and sulfur dioxide yielded 2-butyl-11 β ,17 α ,20 β ,21-tetrahydroxy-4-pregn-3-one 21-acetate.

(f) 2 - pentyl - 11 β ,21 - dihydroxy - 4,17(20) - [trans]-pregnadien-3-one 21-acetate and hydrolyzing the thus produced 17(20)-osmate with water and sulfur dioxide

yielded 2-pentyl-11 β ,17 α ,20 β ,21-tetrahydroxy-4-pregn-3-one 21-acetate.

(g) 2 - hexyl - 11 β ,21 - dihydroxy - 4,17(20) - [trans]-pregnadien-3-one 21-acetate and hydrolyzing the thus produced 17(20)-osmate with water and sulfur dioxide yielded 2-hexyl-11 β ,17 α ,20 β ,21-tetrahydroxy-4-pregn-3-one 21-acetate.

(h) 2 - heptyl - 11 β ,21 - dihydroxy-4,17(20)-[trans]-pregnadien-3-one 21-acetate and hydrolyzing the thus produced 17(20)-osmate with water and sulfur dioxide yielded 2-heptyl-11 β ,17 α ,20 β ,21-tetrahydroxy-4-pregn-3-one 21-acetate.

(i) 2 - octyl - 11 β ,21 - dihydroxy - 4,17(20) - [trans]-pregnadien-3-one 21-acetate and hydrolyzing the thus produced 17(20)-osmate with water and sulfur dioxide yielded 2-octyl-11 β ,17 α ,20 β ,21-tetrahydroxy-4-pregn-3-one 21-acetate.

(j) 2 - benzyl - 11 β ,21 - dihydroxy - 4,17(20) - [trans]-pregnadien-3-one 21-acetate and hydrolyzing the thus produced 17(20)-osmate with water and sulfur dioxide yielded 2-benzyl-11 β ,17 α ,20 β ,21-tetrahydroxy-4-pregn-3-one 21-acetate.

(k) 2 - phenyl - 11 β ,21 - dihydroxy-4,17(20)-[trans]-pregnadien-3-one 21-acetate and hydrolyzing the thus produced 17(20)-osmate with water and sulfur dioxide yielded 2-phenyl-11 β ,17 α ,20 β ,21-tetrahydroxy-4-pregn-3-one 21-acetate.

(l) 2 - methyl - 11 β ,21 - dihydroxy-4,17(20)-[trans]-pregnadien-3-one 21-propionate and hydrolyzing the thus produced 17(20)-osmate with water and sulfur dioxide yielded 2-methyl-11 β ,17 α ,20 β ,21-tetrahydroxy-4-pregn-3-one 21-propionate.

(m) 2 - methyl - 11 β ,21 - dihydroxy-4,17(20)-[trans]-pregnadien-3-one 21-benzoate and hydrolyzing the thus produced 17(20)-osmate with water and sulfur dioxide yielded 2 - methyl - 11 β ,17 α ,20 β ,21 - tetrahydroxy - 4-pregnene-3-one 21-benzoate.

(n) 2 - methyl - 11 β ,21 - dihydroxy-4,17(20)-[trans]-pregnadien-3-one 21-phenylacetate and hydrolyzing the thus produced 17(20)-osmate with water and sulfur dioxide yielded 2-methyl-11 β ,17 α ,20 β ,21-tetrahydroxy-4-pregn-3-one 21-phenylacetate.

(o) 2 - methyl - 11 β ,21 - dihydroxy-4,17(20)-[trans]-pregnadien-3-one 21-trimethylacetate and hydrolyzing the thus produced 17(20)-osmate with water and sulfur dioxide yielded 2-methyl-11 β ,17 α ,20 β ,21-tetrahydroxy-4-pregn-3-one 21-trimethylacetate.

In the same manner as shown in Example 9, other 2 - lower-alkyl - 11 β ,21 - dihydroxy - 4,17(20) - [trans]-pregnadien-3-ones may be treated with osmium tetroxide and tertiary butyl alcohol in pyridine or dioxane and pyridine to give the corresponding 17(20)-osmate, which with water and sulfur dioxide (sulfurous acid) are decomposed to give the corresponding 2-lower-alkyl-11 β ,17 α ,20 β ,21-tetrahydroxy - 4 - pregnene - 3 - one 21-acylates. Thus obtained more important acylates include the 2 - methyl - 11 β ,17 α ,20 β ,21 - tetrahydroxy-4-pregn-3-one 21-acylates wherein the 21-acylate can be butyrate, isobutyrate, valerate, isovalerate, hexanoate, heptanoate, octanoate, phenylpropionate, toluate, cinnamate, lactate, acid tartrate, dihydrogencitrate, chloroacetate, bromoacetate, fluoroacetate, iodoacetate, dichloroacetate, dienepentylacetate, triethylacetate or the like.

EXAMPLE 10

2-methyl-11 β ,17 α ,20 β ,21-tetrahydroxy-4-pregn-3-one 20,21-diacetate:

A mixture of two grams of 2-methyl-11 β ,17 α ,20 β ,21-tetrahydroxy-4-pregn-3-one 21-acetate, 25 milliliters of pyridine and 25 milliliters of acetic anhydride was maintained at room temperature for a period of twenty hours; thereafter the reaction mixture was poured into ice water to give a precipitate which was recovered by filtration. The thus obtained crude crystalline material was recrystallized from ethyl acetate-Skellysolve B hexanes to

give pure 2 - methyl - $11\beta,17\alpha,20\beta,21$ - tetrahydroxy-4-pregnene-3-one 20,21 - diacetate 2 - methyl - $11\beta,17\alpha$ -dihydroxy-20 $\beta,21$ -diacetoxy-4-pregnene-3-one of melting point 221-223 degrees centigrade; rotation $[\alpha]_D$ plus 180 degrees (acetone).

Analysis.—Calcd. for $C_{26}H_{38}O_7$: C, 67.51; H, 8.28. Found: C, 67.53; H, 8.19.

EXAMPLE 11

In the same manner as shown in Example 10:

(a) 2 - methyl - $11\beta,17\alpha,20\beta,21$ - tetrahydroxy - 4-pregnene-3-one 21-propionate was reacted with propionic anhydride in pyridine to give 2-methyl- $11\beta,17\alpha,20\beta,21$ -tetrahydroxy-4-pregnene-3-one 20 $\beta,21$ -dipropionate.

(b) 2 - methyl - $11\beta,17\alpha,20\beta,21$ - tetrahydroxy - 4-pregnene-3-one 21-benzoate was reacted with benzoyl chloride in pyridine to give 2-methyl- $11\beta,17\alpha,20\beta,21$ -tetrahydroxy-4-pregnene-3-one 20 $\beta,21$ -dibenzoate.

(c) 2 - methyl - $11\beta,17\alpha,20\beta,21$ - tetrahydroxy - 4-pregnene-3-one 21-phenylacetate was reacted with phenyl acetyl bromide in pyridine to give 2-methyl- $11\beta,17\alpha,20\beta,21$ -tetrahydroxy-4-pregnene-3-one 20 $\beta,21$ -diphenylacetate.

(d) 2 - methyl - $11\beta,17\alpha,20\beta,21$ - tetrahydroxy - 4-pregnene-3-one 21-toluenesulfonate was reacted with toluenesulfonyl chloride in pyridine to give 2-methyl- $11\beta,17\alpha,20\beta,21$ -tetrahydroxy-4-pregnene-3-one 20 $\beta,21$ -ditoluenesulfonate.

(e) 2 - ethyl - $11\beta,17\alpha,20\beta,21$ - tetrahydroxy - 4-pregnene-3-one 21-acetate was reacted with benzoyl chloride to give 2 - ethyl - $11\beta,17\alpha,20\beta,21$ - tetrahydroxy-4-pregnene-3-one 20 β -benzoate, 21-acetate.

(f) 2 - propyl - $11\beta,17\alpha,20\beta,21$ - tetrahydroxy-4-pregnene-3-one 21-acetate was reacted with butyryl chloride to give 2-propyl- $11\beta,17\alpha,20\beta,21$ -tetrahydroxy-4-pregnene-3-one 20 β -butyrate, 21-acetate.

(g) 2 - benzyl - $11\beta,17\alpha,20\beta,21$ - tetrahydroxy-4-pregnene-3-one 21-acetate was reacted with valeryl chloride to give 2 - benzyl - $11\beta,17\alpha,20\beta,21$ - tetrahydroxy - 4-pregnene-3-one 20 β -valerate, 21-acetate.

In the same manner as given in Examples 10 and 11 other 2 - lower-alkyl - $11\beta,17\alpha,20\beta,21$ - tetrahydroxy - 4-pregnene-3-one 20 $\beta,21$ -diacylates are obtained by esterifying the 2-lower-alkyl- $11\beta,17\alpha,20\beta,21$ -tetrahydroxy-4-pregnene-3-one 21-acylates, dissolved in pyridine or in a neutral solvent such as benzene, toluene, ether or the like, with an acylating agent such as a halide or anhydride of an organic carboxylic acid, preferably hydrocarbon carboxylic acid containing from one to eight carbon atoms, inclusive. Such 2-lower-alkyl- $11\beta,17\alpha,20\beta,21$ -tetrahydroxy-4-pregnene-3-one 20 $\beta,21$ -diacylates include: 2 - butyl - $11\beta,17\alpha,20\beta,21$ - tetrahydroxy - 4-pregnene-3-one 20 β -(2-furoate), 21-acetate, 2-benzyl- $11\beta,17\alpha,20\beta,21$ -tetrahydroxy-4-pregnene-3-one 20 β -nicotinate, 21-acetate, 2-methyl- $11\beta,17\alpha,20\beta,21$ -tetrahydroxy-4-pregnene-3-one 20 β -acetate, 21-trimethylacetate, 2-methyl- $11\beta,17\alpha,20\beta,21$ -tetrahydroxy-4-pregnene-3-one 20 β -propionate, 21-dineopentylacetate and the like.

EXAMPLE 12

2-methyl- $17\alpha,20\beta,21$ -trihydroxy-4-pregnene-3,11-dione 20,21-diacetate

A solution of 462.5 milligrams of 2-methyl- $11\beta,17\alpha,20\beta,21$ -tetrahydroxy-4-pregnene-3-one 20,21-diacetate in thirty milliliters of acetone and two milliliters of water was mixed with 311 milligrams of N-bromoacetamide. After stirring for three hours the reaction mixture was poured into thirty milliliters of water containing 600 milligrams of sodium sulfite and stirred for a period of one hour. The acetone was distilled at reduced pressure and the solution was extracted with methylene chloride. Evaporation of the solvent gave an oil which could not be recrystallized but the infrared spectrum was in agreement with the proposed structure for 2-methyl- $17\alpha,20\beta,21$ - trihydroxy-4-pregnene-3,11-dione 20,21-diacetate. Rotation was $[\alpha]_D$ plus 130 degrees (acetone).

EXAMPLE 13

2 - methyl - $17\alpha,20\beta,21$ - trihydroxy - 4 - pregnene - 3,11-dione 20 $\beta,21$ - diacetate from $11\beta,21$ - dihydroxy-4,17(20)-[*cis*]-pregnadien-3-one 21-acetate

(a) 2 - glyoxalylation of 11β - hydroxy - 21 - acetoxy-4,17(20)-[*cis*]-pregnadien-3-one.—A solution of 18.62 grams (0.05 mole) of 11β -hydroxy-21-acetoxy-4,17(20)-pregnadien-3-one was prepared in 300 milliliters of dry tertiary butyl alcohol by heating the mixture at seventy degrees centigrade. The solution was cooled to 55 degrees centigrade and to the stirred solution, protected from atmospheric oxygen by bubbling nitrogen therethrough, was added 11.5 grams (0.10 mole) of methyl oxalate followed by a solution of 4.05 grams (0.075 mole) of sodium methoxide, dissolved in sixteen milliliters of methanol. A thick, pale yellow precipitate soon appeared. Stirring was continued for ten minutes and the mixture was then diluted with 300 milliliters of anhydrous ether. Stirring was continued for an additional fifteen minutes and the mixture then filtered. The pale yellow-green precipitate was washed and dried at room temperature (22-25 degrees centigrade) in a vacuum. The yield of about 24 grams of precipitate consisted primarily of a sodium enolate of 2-methoxyoxalyl- 11β -hydroxy-21-acetoxy-4,17(20)-[*cis*]-pregnadien-3-one.

The precipitate was dissolved in 250 milliliters of water and the solution acidified with dilute hydrochloric acid. The resulting precipitate was collected by filtration, washed with water and dried. There was thus obtained 18.71 grams of an amorphous powder consisting essentially of 2-methoxyoxalyl- 11β -hydroxy-21-acetoxy-4,17(20)-[*cis*]-pregnadien-3-one which melted at eighty to 95 degrees centigrade and which gave a positive red-brown ferric chloride test.

(b) 2-methyl-2-methoxyoxalyl- 11β -hydroxy-21-acetoxy-4,17(20)-[*cis*]-pregnadien-3-one.—A mixture of 4.70 grams of crude 2-methoxyoxalyl- 11β -hydroxy-4,17(20)-pregnadien-3-one, obtained according to the method of Example 1, ten grams of anhydrous potassium carbonate, fifteen milliliters of methyl iodide and 100 milliliters of acetone were stirred at about 25 degrees centigrade for forty hours. Water was then added and the mixture extracted thoroughly with methylene chloride. The extract was washed with water, dried and the solvent distilled to leave a glassy residue of 2-methyl-2-methoxyoxalyl - 11β - hydroxy-21-acetoxy-4,17(20)-pregnadien-3-one.

(c) 2-methyl- $11\beta,21$ -dihydroxy-4,17(20)-[*cis*]-pregnadien-3-one.—The glassy residue of crude 2-methyl-2-methoxyoxalyl- 11β -hydroxy-21-acetoxy-4,17(20)-pregnadien-3-one, obtained according to the method described above, was dissolved in fifty milliliters of methanol to which was then added three milliliters of a 25 percent solution of sodium methoxide in methanol. The now red solution was stirred for a period of two hours at about 25 degrees centigrade. The mixture was then diluted with about 200 milliliters of water and extracted thoroughly with methylene chloride. The combined methylene chloride extracts were washed with water, dried and the solvent then distilled therefrom, leaving a steroid residue of 2-methyl- $11\beta,21$ -dihydroxy-4,17(20)-[*cis*]-pregnadien-3-one. The thus-produced 2-methyl- $11\beta,21$ -dihydroxy-4,17(20) - [*cis*] - pregnadien-3-one is purified by chromatography over Florisil synthetic magnesium silicate developed with Skellysolve B hexanes containing increasing proportions of acetone.

(d) 2-methyl- 11β -hydroxy-21-acetoxy-4,17(20)-[*cis*]-pregnadien-3-one.—The crude residue obtained from the reversal reaction was dissolved in a mixture of ten milliliters of acetic anhydride and ten milliliters of dry pyridine. The mixture was maintained at about 25 degrees centigrade for about sixteen hours. The excess acetic anhydride was then decomposed with ice water and the resulting gummy precipitate was extracted with benzene.

The benzene solution was washed with cold dilute hydrochloric acid, cold aqueous sodium bicarbonate, water, and then dried. The dried benzene solution was poured over a chromatographic column of 100 grams of Florisil synthetic magnesium silicate. The column was developed with 1350 milliliters of Skellysolve B hexane hydrocarbons containing five percent acetone followed by 750 milliliters of Skellysolve B plus 7.5 percent acetone and then 150 milliliters of acetone. The eluates were collected in 150 milliliter fractions. Eluate fractions 4 to 8 contained a total of 1.71 grams, a yield of 44 percent, calculated on the starting 2-methoxyxalyl-11 β ,21-dihydroxy-4,17(20)-pregnadien-3-one, of crystalline 2-methyl-11 β -hydroxy-21-acetoxy-4,17(20)-pregnadien-3-one. Recrystallization of this product gave 2-methyl-11 β -hydroxy-21-acetoxy-4,17(20)-pregnadien-3-one melting at 182 to 184.5 degrees centigrade, having an $[\alpha]_D$ of plus 145 degrees in chloroform, an ultraviolet absorption of 15,025 millimicrons and the analysis below.

Analysis.—Calcd. for $C_{24}H_{34}O_4$: C, 74.57; H, 8.87. Found: C, 74.32; H, 8.79.

(e) 2-methyl-21-hydroxy-4,17(20)-[*cis*]-pregnadiene-3,11-dione 21-acetate.—A solution of 1.3 grams of 2-methyl-11 β ,21-dihydroxy-4,17(20)-[*cis*]-pregnadien-3-one, 21-acetate in 120 milliliters of glacial acetic acid was prepared at a temperature of fifteen degrees centigrade. Thereto was added a solution of 260 milligrams of chromic acid in 0.5 milliliter of water. The temperature of the reaction mixture did not rise above eighteen degrees centigrade. The solution was stirred for a period of ten minutes and then allowed to stand for another period of ten minutes. The crystalline crop was precipitated with the addition of 600 milliliters of water yielding 1.21 grams (93 percent yield) of 2-methyl-21-hydroxy-4,17(20)-[*cis*]-pregnadiene-3,11-dione 21-acetate of melting point 155-158 degrees.

(f) 2-methyl-17 α ,20-epoxy-21-hydroxy-4-pregnene-3,11-dione 21-acetate.—A mixture was prepared at a temperature of about ten degrees centigrade containing 0.2 gram of 2-methyl-21-hydroxy-4,17(20)-[*cis*]-pregnadiene-3,11-dione 21-acetate, ten milliliters of chloroform and one milliliter of peracetic acid. This mixture was maintained at about five degrees centigrade for a period of eighteen hours. The solution was thereupon diluted with fifty milliliters of methylene chloride, washed once with water and once with four percent aqueous sodium bicarbonate solution, then water and dried over anhydrous sodium sulfate. Recrystallization of the crude product from acetone-Skellysolve B gave pure 2-methyl-17 α ,20 α -epoxy-21-hydroxy-4-pregnene-3,11-dione 21-acetate of melting point 181 to 188 degrees centigrade.

(g) 17 α ,20 β ,21-trihydroxy-2-methyl-4-pregnene-3,11-dione 21-acetate.—Three grams of 2-methyl-17 α ,20 α -epoxy-21-hydroxy-4-pregnene-3,11-dione 21-acetate, dissolved in 150 milliliters of dioxane, was refluxed with ten milliliters of 3.5 normal sulfuric acid for a period of one hour. Thereafter the mixture was concentrated to about twenty milliliters of volume at reduced pressure, then diluted with 200 milliliters of methylene chloride and washed with water and aqueous four percent sodium bicarbonate. After filtration through anhydrous sodium sulfate, the solution was distilled to dryness at reduced pressure giving 17 α ,20 β ,21-trihydroxy-2-methyl-4-pregnene-3,11-dione 21-acetate with an infrared spectrum in chloroform which was consistent with that expected for 2-methyl-17 α ,20 β ,21-trihydroxy-4-pregnene-3,11-dione 21-acetate.

(h) 2-methyl-17 α ,20 β ,21-trihydroxy-4-pregnene-3,11-dione 20 β ,21-diacetate.—2.5 grams of 2-methyl-17 α ,20 β ,21-trihydroxy-4-pregnene-3,11-dione 21-acetate was dissolved in fifteen milliliters of pyridine and thereto was added fifteen milliliters of acetic anhydride. The mixture was maintained at room temperature for sixteen hours and then poured into ice water and extracted with methylene chloride. The methylene chloride extracts were

washed with water, dried over anhydrous sodium sulfate and evaporated to give an oil having a rotation of $[\alpha]_D$ of plus 130 degrees (acetone).

Analysis.—Calcd. for $C_{25}H_{34}O_7$: C, 67.80; H, 7.88. Found: C, 67.64; H, 8.12.

EXAMPLE 14

2-methyl-17 α ,20 β ,21-trihydroxy-4-pregnene-3,11-dione

A solution containing one gram of 2-methyl-17 α ,20 β ,21-trihydroxy-4-pregnene-3,11-dione 21-acetate, 25 milliliters of 95 percent alcohol and one gram of potassium carbonate was refluxed for a period of thirty minutes in a nitrogen atmosphere and thereupon poured into 100 milliliters of ice water. The mixture was then extracted with methylene chloride, the methylene chloride extracts were washed with water, dried over anhydrous sodium sulfate and evaporated to give an oil, 2-methyl-17 α ,20 β ,21-trihydroxy-4-pregnene-3,11-dione. Infrared spectrum in chloroform confirmed the structure.

EXAMPLE 15

2-methyl-11 β ,17 α ,20 β ,21-tetrahydroxy-4-pregnene-3-one 21-trimethylacetate

One gram of 2-methyl-11 β ,17 α ,20 β ,21-tetrahydroxy-4-pregnene-3-one (Example 9a) was dissolved in ten milliliters of pyridine. Thereto was added one milliliter of trimethylacetyl chloride and the mixture was heated on the water bath for a period of three hours at a temperature of forty to fifty degrees. Thereafter the reaction mixture was poured into excess cold water and extracted with methylene chloride. The methylene chloride extracts were washed with dilute sodium bicarbonate, water, dried over anhydrous sodium sulfate and evaporated to give the crude trimethylacetate. The crude trimethylacetate was recrystallized from acetone and Skellysolve B hexanes to give pure 2-methyl-11 β ,17 α ,20 β ,21-tetrahydroxy-4-pregnene-3-one 21-trimethylacetate.

Treating 2-methyl-17 α ,20 β ,21-trihydroxy-4-pregnene-3,11-dione with trimethylacetyl bromide as shown in Example 15, produces 2-methyl-17 α ,20 β ,21-trihydroxy-4-pregnene-3,11-dione 21-trimethylacetate.

In the same manner other halides of sterically hindered acids such as triethylacetyl chloride, dineopentylacetyl chloride or bromide or the like may be used to selectively esterify the primary 21-hydroxyl group without producing esters of the 20 β -hydroxyl group.

EXAMPLE 16

2-methylhydrocortisone 21-trimethylacetate

A mixture of one gram of 2-methyl-11 β ,17 α ,20 β ,21-tetrahydroxy-4-pregnene-3-one, 21-trimethylacetate, one gram of manganese dioxide freshly prepared by the method of Attenburrow et al., Journ. Chem. Soc., 1094 (1952), and 25 milliliters of methylene chloride was refluxed for a period of six hours. Thereafter the reaction mixture was filtered, the precipitate washed with three five-milliliter portions of methylene chloride and the filtrate and washings combined and evaporated. The thus obtained material was purified by repeated recrystallization from acetone and Skellysolve B to give pure 2-methyl-11 β ,17 α ,21-trihydroxy-4-pregnene-3,20-dione 21-trimethylacetate (2-methylhydrocortisone 21-trimethylacetate).

EXAMPLE 17

2-methylcortisone trimethylacetate

In the same manner as shown in Example 16, 2-methyl-17 α ,20 β ,21-trihydroxy-4-pregnene-3,11-dione 21-trimethylacetate was oxidized with manganese dioxide in methylene dichloride to give 2-methyl-17 α ,21-dihydroxy-4-pregnene-3,11,20-trione 21-triethylacetate.

In the manner of Examples 16 and 17, other esters of 2-methylhydrocortisone and 2-methylcortisone and other 2-lower-alkyl cortisone and hydrocortisone esters are prepared by either oxidizing the 20 β -hydroxy group of the

23

2-lower-alkyl-11 β ,17 α ,20 β ,21 - tetrahydroxy-4-pregnene-3-one or lower-alkyl - 17 α ,20 β ,21 - trihydroxy-4-pregnene-3,11-dione or by hydrolyzing and esterifying with other acyl halides the 2-methylhydrocortisone acetate and 2-methylcortisone trimethylacetate shown in Examples 16 and 17.

EXAMPLE 18

2-methyl-17 α ,20 β ,21-trihydroxy - 4,9(11) - pregnadien-3-one 20 β ,21-diacetate (2-methyl-17 α -hydroxy-20 β ,21-diacetoxy-4,9(11)-pregnadien-3-one

A mixture of one gram of 2-methyl-11 β ,17 α ,20 β ,21-tetrahydroxy-4-pregnene-3-one 20 β ,21-diacetate, 60 milligrams of N-bromoacetamide and six milliliters of pyridine was stirred in the dark for a period of five minutes. The mixture was then cooled in an ice water bath and a stream of sulfur dioxide was directed under the surface of the stirred mixture until a negative potassium iodide-starch test was obtained. Fifty milliliters of water was then added to the mixture and the mixture was maintained at about five degrees centigrade for thirty minutes. The precipitated white solid was filtered, washed with water and dried under vacuum. After recrystallization from acetone there was obtained pure 2-methyl-17 α ,20 β ,21-trihydroxy-4,9(11)-pregnadiene-3,20-dione 20,21-diacetate. Using instead of the 20,21-diacetate of 2-methyl-11 β ,17 α ,20 β ,21-tetrahydroxy - 4 - pregnen-3-one the dipropionate, the dibutyrate, the dibenzylate and the like, the corresponding 2-methyl - 17 α ,20 β ,21 - trihydroxy-4,9(11)-pregnadien-3-one 20 β ,21-dipropionate, dibutyrate, 30 dibenzylate and the like is obtained.

Hydrolyzing in a nitrogen atmosphere with potassium carbonate in methanol or ethanol, 2-methyl-17 α ,20 β ,21-trihydroxy - 4,9(11) - pregnadien-3-one 20 β ,21-diacetate produces the corresponding free alcohol, 2-methyl-17 α ,20 β ,21-trihydroxy-4,9(11)-pregnadien-3-one.

Reesterification of 2-methyl-17 α ,20 β ,21-trihydroxy-4,9(11)-pregnadien-3-one with anhydrides or halides of hydrocarbon carboxylic acid of a straight chain structure produces the corresponding diacylates. If hydrocarbon carboxylic acids are used which have sterically hindered groups such as trimethylacetyl chloride, triethylacetyl chloride, dineopentylacetyl bromide or the like, the corresponding 21-monoesters of 2-methyl-17 α ,20 β ,21-trihydroxy-4,9(11)-pregnadien-3-one are obtained.

EXAMPLE 19

In the manner shown in Example 18 treating a 2-lower-alkyl - 11 β ,17 α ,20 β ,21 - tetrahydroxy-4-pregnene - 3 - one 20 β ,21-diacylate with N-bromoacetamide in pyridine solution gives the corresponding 2-lower-alkyl-11 β -hypohalo-17 α ,20 β ,21-trihydroxy-4-pregnene-3-one 20 β ,21-diacylate which when decomposed with sulfur dioxide gave the corresponding 2 - lower-alkyl - 17 α ,20 β ,21 - trihydroxy-4,9(11)-pregnadien-3-one 20 β ,21-diacylate.

In this manner from:

(a) 2 - ethyl-11 β ,17 α ,20 β ,21-tetrahydroxy-4-pregnene-3-one 20 β -benzoate, 21-acetate was obtained 2-ethyl-17 α ,20 β ,21-trihydroxy - 4,9(11) - pregnadien-3-one 20 β -benzoate, 21-acetate.

(b) 2 - propyl-11 β ,17 α ,20 β ,21-tetrahydroxy-4-pregnene-3-one 20 β -butyrate, 21-acetate was obtained 2-propyl-17 α ,20 β ,21-trihydroxy - 4,9(11) - pregnadien-3-one 20 β -butyrate, 21-acetate.

(c) 2 - benzyl-11 β ,17 α ,20 β ,21-tetrahydroxy-4-pregnene-3-one 20 β -valerate, 21-acetate was obtained 2-ethyl-17 α ,20 β ,21-trihydroxy - 4,9(11) - pregnadien-3-one 20 β -valerate, 21-acetate.

(d) 2 - butyl - 11 β ,17 α ,20 β ,21-tetrahydroxy-4-pregnene-3-one 20 β ,21 - dipropionate was obtained 2-butyl-17 α ,20 β ,21-trihydroxy-4,9(11)-pregnadien-3-one 20 β ,21-dipropionate.

(e) 2 - hexyl-11 β ,17 α ,20 β ,21-tetrahydroxy-4-pregnene-3-one 20 β ,21-diphenylpropionate was obtained 2-hexyl-17 α ,20 β ,21-trihydroxy-4,9(11)-pregnadien-3-one 20 β ,21-diphenylpropionate.

24

(f) 2 - octyl-11 β ,17 α ,20 β ,21-tetrahydroxy-4-pregnene-3-one 20 β ,21 - dihexanoate was obtained 2 - octyl-17 α ,20 β ,21-trihydroxy-4,9(11)-pregnadien-3-one 20 β ,21-dihexanoate.

EXAMPLE 20

2-methyl-9 α -bromo-11 β ,17 α ,20 β ,21-tetrahydroxy-4-pregnene-3-one 20 β ,21-diacetate.

A solution of one gram of 2-methyl-17 α ,20 β ,21-trihydroxy-4,9(11)-pregnadien-3-one 20 β ,21-diacetate, dissolved in forty milliliters of methylene chloride, was reacted with two milliliters of 71 percent perchloric acid in twenty milliliters of water and thereto was added 412 milligrams of N-bromoacetamide in 100 milliliters of tertiary butyl alcohol. The solution was maintained at room temperature for a period of twenty minutes and then mixed with a solution of 0.50 gram of sodium sulfite in 24 milliliters of water. The mixture was distilled at reduced pressure and the residual solution became 20 cloudy. The product was then precipitated by the addition of 200 milliliters of a mixture of ice and water. The white crystalline precipitate of 2-methyl-9 α -bromo-11 β ,17 α ,20 β ,21-tetrahydroxy-4-pregnene-3,20-dione 20 β ,21-diacetate was filtered, washed with water and then dried at room temperature in a vacuum. Recrystallization from a mixture of acetone and Skellysolve B gave pure 2-methyl-9 α -bromo-11 β ,17 α ,20 β ,21-tetrahydroxy - 4 - pregnen-3-one 20 β ,21-diacetate (2-methyl-9 α -bromo-11 β ,17 α -dihydroxy-20 β ,21-diacetoxy-4-pregnene-3-one).

EXAMPLE 21

2-ethyl-9 α -chloro-11 β ,17 α ,20 β ,21-tetrahydroxy-4-pregnene-3-one 20 β -benzoate, 21-acetate

A mixture of one gram of 2-ethyl-17 α ,20 β ,21-trihydroxy-4,9(11)-pregnadien-3-one 20 β -benzoate, 21-acetate, dissolved in fifty milliliters of methylene chloride, was reacted with a solution of two milliliters of 71 percent perchloric acid in ten milliliters of water and thereto was added N-chloro-succinimide in 100 milliliters of tertiary butyl alcohol. The solution was maintained at twenty degrees centigrade for a period of one hour then mixed with half a gram of sodium sulfite and twelve milliliters of water. The mixture was distilled at reduced pressure and the product precipitated with the addition of excess water. The white crystalline precipitate was filtered, washed, dried and recrystallized from acetone and Skellysolve B hexanes to give pure 2-ethyl-9 α -chloro-11 β ,17 α ,20 β ,21-tetrahydroxy-4-pregnene-3-one 20 β -benzoate, 21-acetate (2-ethyl-9 α -chloro-11 β ,17 α -dihydroxy-20 β -benzoxy-21-acetoxy-4-pregnene-3-one).

EXAMPLE 22

In the same manner as shown in Examples 20 and 21, reacting 2-lower-alkyl-17 α ,20 β ,21 - trihydroxy - 4,9(11)-pregnadien-3-one 20 β ,21-diacylate in solution with a N-halo acid amide in the presence of acid to produce in situ a hypohalous acid yields the corresponding 2-lower-alkyl-9 α -halo-11 β ,17 α ,20 β ,21-tetrahydroxy-4 - pregnen-3-one 20 β ,21-diacylate wherein the halogen atom in the 9 α -position has an atomic weight between 34 and 130. Representative 9 α -halo compounds thus obtained are: the 2-propyl-9 α -halo-11 β ,17 α ,20 β ,21 - tetrahydroxy - 4-pregnene-3-one 20 β -butyrate, 21-acetate, the 2-benzyl-9 α -halo-11 β ,17 α ,20 β ,21-tetrahydroxy-4-pregnene-3-one 20 β -valerate, 21-acetate, the 2-butyl-9 α -halo-11 β ,17 α ,20 β ,21 - tetrahydroxy-4-pregnene-3-one 20 β ,21-dipropionate, the 2-hexyl-9 α -halo-11 β ,17 α ,20 β ,21-tetrahydroxy-4 - pregnen-3-one 20 β ,21-diphenylpropionate, the 2-octyl-9 α -halo-11 β ,17 α ,20 β ,21-tetrahydroxy-4-pregnene-3-one 20 β ,21-dioctanoate wherein the halo atom is bromo, chloro, or iodo.

EXAMPLE 23

2-methyl-9 α -bromo-17 α ,20 β ,21-trihydroxy-4-pregnene-3,11-dione 20 β ,21-diacetate

A solution was prepared containing one half gram of 2-methyl-11 β ,17 α ,20 β ,21-tetrahydroxy-4-pregnene - 3 - one

$20\beta,21$ -diacetate dissolved in five milliliters of glacial acetic acid. To this solution was added 0.3 gram of chromic anhydride, dissolved in two milliliters of acetic acid, and one milliliter of water. The thus obtained solution was maintained at room temperature for a period of three hours. Thereafter one milliliter of methanol was added, the solution was shaken and poured into twenty milliliters of ice water. Sodium bicarbonate solution was added to neutralize the solution and the solution was then filtered to give a crude material which was recrystallized from acetone-Skellysolve B hexanes to give pure 2 -methyl- 9α -bromo- $17\alpha,20\beta,21$ -trihydroxy- 4 -pregnene- $3,11$ -dione $20\beta,21$ -diacetate.

EXAMPLE 24

2-ethyl-9 α -chloro-17 α ,20 β ,21-trihydroxy-4-pregnene-3,11-dione 20 β -benzoate, 21-acetate

In the same manner as shown in Example 22 oxidizing 2-ethyl-9 α -chloro-11 β ,17 α ,20 β ,21 - tetrahydroxy - 4-pregnene-3-one 20 β -benzoate, 21-acetate with chromic acid in acetic acid solution produces the corresponding 2-ethyl-9 α -chloro-17 α ,20 β ,21-trihydroxy - 4-pregnene-3,11-dione 20 β -benzoate, 21-acetate.

In the same manner as shown in Examples 22 and 23, other 2-lower-alkyl-17 α ,20 β ,21-trihydroxy-4-pregnene-3,11-dione 20 β ,21-diacylates are prepared by oxidizing the corresponding 2-lower-alkyl - 11 β ,17 α ,20 β ,21 - tetrahydroxy-4-pregn-3-one 20 β ,21 - diacylates. Representative compounds thus obtained comprise the 2-lower-alkyl-17 α ,20 β ,21-trihydroxy-4-pregnene-3,11-dione 20 β ,21 - diacylates wherein the alkyl group is methyl, ethyl, propyl, isopropyl, butyl, isobutyl, pentyl, hexyl, heptyl, octyl, phenyl, benzyl or the like and wherein the acylate may be a diacetate, dipropionate, dibutyrate, dibenzoate, diphenylpropionate, diphenylacetate, dianisate, dinicotinate or the like or a mixed ester such as a 20 β -acetate, 21-propionate; 20 β -propionate, 21-benzoate; 20 β -butyrate, 21-hexanoate; 20 β -valerate, 21-acetate and similar combinations.

Hydrolyzing 2 - methyl - 9 α - bromo-17 α ,20 β ,21-trihydroxy-4-pregnene-3,11-dione 20 β ,21-diacetate with potassium carbonate in ethanol under nitrogen atmosphere as shown in Example 14 produces the corresponding free triol, 2-methyl-9 α -bromo-17 α ,20 β ,21-trihydroxy - 4-pregnene-3,11-dione.

In the same manner given in Example 15 selective esterification of 2-methyl-9 α -bromo-17 α ,20 β ,21-trihydroxy-4-pregnene-3,11-dione with trimethylacetyl chloride, triethylacetyl chloride, dineopentylacetyl chloride or bromide, or with some similar halide of a hindered organic acid produced the corresponding 2-methyl-9 α -bromo-17 α ,20 β ,21-trihydroxy-4-pregnene-3,11-dione 21 - trimethylacetate, triethylacetate, dineopentylacetate or the like.

In the manner shown in Example 16, oxidation of the 21-monoesters of 2-methyl - 9 α -bromo-17 α ,20 β ,21-trihydroxy-4-pregnene-3,11-dione 21-trimethylacetate, triethylacetate of dineopentylacetate with manganese dioxide in a solvent such as hexane, heptane, Skellysolve B hexanes, methylene chloride, ethylene dichloride, chloroform, or the like produces the corresponding 2-methyl-9 α -bromo cortisone (2-methyl-9 α -bromo - 17 α ,21 - dihydroxy - 4-pregnene-3,11,20-trione) trimethylacetate, triethylacetate, dineopentylacetate. In similar manner the chloro or iodo compounds of 2-lower-alkyl cortisone esters can be made.

Similarly oxidizing 21-monoesters of 2-lower-alkyl-11 β , 17 α ,20 β ,21-tetrahydroxy-4-pregnen-3-ones with manganese dioxide in an organic solvent such as methylene chloride, ethylene chloride, hexane, heptane or the like produces the corresponding 2-lower-alkyl-9 α -halo-11 β ,17 α ,21-trihydroxy-4-pregnen-3,20-dione 21-acylate wherein the lower-alkyl group, the halo group and the acrylate are defined as in the preceding 2-lower-alkyl-9 α -halocortisone acylates. In this manner 2-lower-alkyl-9 α -halohydrocortisone esters are produced such as for example 2-methyl-9 α -bromohydrocortisone 21-trimethyl-acetate, 2-methyl-9 α -

chlorohydrocortisone, 21-trimethylacetate, 2-ethyl-9 α -bromohydrocortisone, 21-dineopentylacetate, or the like.

EXAMPLE 25

5 2-methyl-9 β ,11 β -epoxy-17 α ,20 β ,21-trihydroxy-4-pregnene-3-one 20 β ,21-diacetate (2-methyl-9 β ,11 β -epoxy-17 α -hydroxy-20 β ,21-diacetoxypregnene-3-one).

A mixture of 0.5 gram of 2-methyl-9 α -bromo-11 β ,17 α ,20 β ,21-tetrahydroxy-4-pregnen-3-one, 20 β ,21-diacetate, 10 0.5 gram of anhydrous potassium acetate and twenty milliliters of acetone was heated at its refluxing temperature for a period of five hours. The cold mixture was thereupon poured into water and extracted with methylene chloride. The methylene chloride extracts were dried 15 over anhydrous sodium sulfate and then evaporated. The thus obtained residue was recrystallized from acetone and Skellysolve B three times to give 2-methyl-9 β ,11 β -epoxy-17 α ,20 β ,21-trihydroxy,4-pregnen-3-one 20 β ,21-diacetate.

EXAMPLE 26

20 *2-ethyl-9 β ,11 β -epoxy-17 α ,20 β ,21-trihydroxy-4-pregnene-3-one, 20-benzoate, 21-acetate*

In the same manner as shown in Example 25, 2-ethyl-9 α -chloro-11 β ,17 α ,20 β ,21-tetrahydroxy-4-pregnen-3-one 20-benzoate, 21 acetate was heated with anhydrous potassium acetate in acetone solution to give 2-ethyl-9 β ,11 β -epoxy-17 α ,20 β ,21-trihydroxy-4-pregnen-3-one 20 β -benzoate, 21-acetate.

30 2 - lower - alkyl - 9α -halo- $11\beta,17\alpha,20\beta,21$ -tetrahydroxy-4-pregnens-3-one 20,21-diacylates with anhydrous potassium acetate or anhydrous sodium acetate in an anhydrous solvent such as acetone, dioxane tertiary butyl alcohol, chloroform or the like at a temperature between fifty degrees and the boiling point of the solvent produces the corresponding 2-lower-alkyl- $9\beta,11\beta$ -epoxy- $17\alpha,20\beta,21$ -tri-hydroxy-4-pregnens-3-one 20,21-diacylates. As starting compounds those 2-lower-alkyl- 9α -halo- $11\beta,17\alpha,20\beta,21$ -tetrahydroxy-4-pregnens-3-one 20,21-diacylates are useful
40 in which the halo atom is of atomic weight 34 to 130, wherein the alkyl group contains from one to eight carbon atoms and wherein the acyl group of the acylate is of an organic carboxylic acid, preferably a hydrocarbon carboxylic acid containing from one to eight carbon atoms inclusive.

EXAMPLE 27

2 - methyl - 9 α - fluoro - 11 β ,17 α ,20 β ,21 - tetrahydroxy-4-pregnен-3-one 20,21-diacetate (2-methyl-9 α -fluoro-11 β ,17 α -dihydroxy-20 β ,21-diacetoxу-4-pregnен-3-one)

50 One gram of 2-methyl-9 β ,11 β -epoxy-17 α ,20 β ,21-trihydroxy-4-pregnen-3-one 20,21-diacetate, dissolved in fifty milliliters of methylene chloride, was treated with five milliliters of 48 percent hydrofluoric acid and 0.5 milliliter of 71 percent perchloric acid at room temperature. 55 The mixture was stirred vigorously for a period of six hours and then poured into an excess of cold aqueous five percent sodium bicarbonate solution. The methylene chloride layer was separated, dried with anhydrous sodium sulfate and thereupon evaporated to give a dry residue of 2 - methyl - 9 α - fluoro-11 β ,17 α ,20 β ,21-tetrahydroxy-4-pregnen-3-one 20,21-diacetate. The material was purified by recrystallization from acetone and Skellysolve B hexanes and the thus purified 2-methyl-9 α -fluoro-60 11 β ,17 α ,20 β ,21-tetrahydroxy-4-pregnene-3-one 20,21 - diacetate of melting point 232.5 to 236 degrees centigrade showed an infrared spectrum in chloroform equal to the one postulated for the proposed compound.

EXAMPLE 28

70 2-ethyl-9 α -fluoro-11 β ,17 α ,20 β ,21-tetrahydroxy-4-pregnene-3-one 20-benzoate

In the same manner as shown in Example 27 reacting 2-ethyl-9 β ,11 β -epoxy-17 α ,20 β ,21-trihydroxy-4-pregnene-3-one 20-benzoate, 21-acetate with hydrofluoric acid in

methylene chloride solution in the presence of a strong acid such as perchloric acid produced 2-ethyl-9 α -fluoro-11 β ,17 α ,20 β ,21-tetrahydroxy-4-pregnen-3-one 20 β -benzoate, 21-acetate.

EXAMPLE 29

In the same manner as shown in Example 27, treating with hydrofluoric acid in methylene chloride in the presence of perchloric acid.

(a) 2-methyl-9 β ,11 β -epoxy-17 α ,20 β ,21-trihydroxy-4-pregnen-3-one 20,21-dipropionate produces 2-methyl-9 α -fluoro-11 β ,17 α ,20 β ,21-tetrahydroxy-4-pregnen-3-one 20,21-dipropionate.

(b) 2-propyl-9 β ,11 β -epoxy-17 α ,20 β ,21-trihydroxy-4-pregnen-3-one 20-butylate, 21-acetate produces 2-propyl-9 α -fluoro-11 β ,17 α ,20 β ,21-tetrahydroxy-4-pregnen-3-one 20-butylate, 21-acetate.

(c) 2-benzyl-9 β ,11 β -epoxy-17 α ,20 β ,21-trihydroxy-4-pregnen-3-one 20-valerate, 21-acetate produces 2-benzyl-9 α -fluoro-11 β ,17 α ,20 β ,21-tetrahydroxy-4-pregnen-3-one 20-valerate, 21-acetate.

(d) 2-butyl-9 β ,11 β -epoxy-17 α ,20 β ,21-trihydroxy-4-pregnen-3-one 20,21-dipropionate produces 2-butyl-9 α -fluoro-11 β ,17 α ,20 β ,21-tetrahydroxy-4-pregnen-3-one 20,21-dipropionate.

(e) 2-hexyl-9 β ,11 β -epoxy-17 α ,20 β ,21-trihydroxy-4-pregnen-3-one 20,21-diphenylpropionate produces 2-hexyl-9 α -fluoro-11 β ,17 α ,20 β ,21-tetrahydroxy-4-pregnen-3-one 20,21-diphenylpropionate.

(f) 2-octyl-9 β ,11 β -epoxy-17 α ,20 β ,21-trihydroxy-4-pregnen-3-one 20,21-dihexanoate produces 2-octyl-9 α -fluoro-11 β ,17 α ,20 β ,21-tetrahydroxy-4-pregnen-3-one 20,21-dihexanoate.

EXAMPLE 30

2-methyl-9 α -iodo-11 β ,17 α ,20 β ,21-tetrahydroxy-4-pregnen-3-one 20,21-diacetate

In the same manner as shown in Example 27 2-methyl-9 β ,11 β -epoxy-17 α ,20 β ,21-trihydroxy-4-pregnen-3-one 20,21-diacetate was dissolved in methylene chloride and reacted with a solution of hydriodic acid in the presence of one percent of perchloric acid calculated on the total volume of solution to give 2-methyl-9 α -iodo-11 β ,17 α ,20 β ,21-tetrahydroxy-4-pregnen-3-one 20,21-diacetate.

In the same manner as shown in Examples 27 through 30 decomposing 2-lower-alkyl-9 β ,11 β -epoxy-17 α ,20 β ,21-trihydroxy-4-pregnen-3-one 20,21-diacetyl wherein the 2-lower-alkyl group is selected from methyl, ethyl, propyl, butyl, hexyl, heptyl, octyl, phenyl and benzyl and the like and wherein the acyl group of the acylate is selected from organic carboxylic acids, preferably hydrocarbon carboxylic acids containing from one to eight carbon atoms, inclusive, with hydrogen halide in the presence of a strong mineral acid such as perchloric, sulfuric acid or a benzenesulfonic acid, illustratively toluenesulfonic acid, produces the corresponding 2-lower-alkyl-9 α -halo-11 β ,17 α ,20 β ,21-tetrahydroxy-4-pregnen-3-one 20,21-diacetyl wherein the halogen atom has an atomic weight from 17 to 130, inclusive.

EXAMPLE 31

2-methyl-9 α -fluoro-11 β ,17 α ,20 β ,21-tetrahydroxy-4-pregnen-3-one

One gram of 2-methyl-9 α -fluoro-11 β ,17 α ,20 β ,21-tetrahydroxy-4-pregnen-3-one 20,21-diacetate was dissolved in fifteen milliliters of methanol. Through the solution was bubbled oxygen free nitrogen for a period of ten minutes. Thereafter was added ten milliliters of methanol containing one gram of potassium carbonate and two milliliters of water. The aqueous alcoholic potassium carbonate solution had previously been purged of air by the same method, that is bubbling oxygen free nitrogen through the solution for a period of ten minutes. The thus obtained mixture is heated in a nitrogen atmosphere to reflux for a period of forty minutes and thereafter cooled and poured into 200 milliliters of cracked ice. The thus

obtained solution was extracted with two 50-milliliter portions of methylene chloride. The methylene chloride extracts were dried, evaporated and the residue was recrystallized from Skellysolve B hexanes-acetone to give 5 pure 2-methyl-9 α -fluoro-11 β ,17 α ,20 β ,21-tetrahydroxy-4-pregnen-3-one.

EXAMPLE 32

2-methyl-9 α -fluoro-11 β ,17 α ,20 β ,21-tetrahydroxy-4-pregnen-3-one 21-trimethylacetate

A mixture containing one gram of 2-methyl-9 α -fluoro-11 β ,17 α ,20 β ,21-tetrahydroxy-4-pregnen-3-one, five milliliters of pyridine and one milliliter of trimethylacetyl chloride was heated to a temperature of fifty degrees for 15 a period of four hours. Thereafter the reaction mixture was poured into thirty milliliters of ice water and the thus obtained precipitate collected on filter and recrystallized from ethyl acetate and Skellysolve B hexanes, to give 20 pure 2-methyl-9 α -fluoro-11 β ,17 α ,20 β ,21-tetrahydroxy-4-pregnen-3-one 21-trimethylacetate.

In a manner similar to Example 31, 2-methyl-9 α -fluoro-11 β ,17 α ,20 β ,21-tetrahydroxy-4-pregnen-3-one may be esterified selectively in the 21-position with halides of sterically hindered acid such as, for example, the chlorides 25 and bromides of trimethylacetic acid, triethylacetic acid, dineopentylacetic acids, or the like.

EXAMPLE 33

2-methyl-9 α -fluoro-17 α ,20 β ,21-trihydroxy-4-pregnen-3,11-dione 20,21-diacetate

A mixture was prepared containing 0.5 gram of 2-methyl-9 α -fluoro-11 β ,17 α ,20 β ,21-tetrahydroxy-4-pregnen-3-one, 20,21-diacetate, 0.2 gram of chromic anhydride, ten milliliters of glacial acetic acid and one-half milliliter 35 of water. This mixture was stirred and thereupon maintained eight hours at room temperature. Thereafter the mixture was poured into fifty milliliters of ice water and neutralized by the addition of dilute sodium hydroxide. The precipitate thus obtained was collected on a filter and 40 recrystallized from ethyl acetate and Skellysolve B hexanes, three times, to give pure 2-methyl-9 α -fluoro-17 α ,20 β ,21-trihydroxy-4-pregnen-3,11-dione 20,21-diacetate (2-methyl-9 α -fluoro-17 α -hydroxy-20 β ,21-diacetoxy-45 pregnene-3,11-dione).

EXAMPLE 34

In the same manner given in Example 33, oxidizing in acetic acid solution with chromic anhydride in the presence of a small amount of water:

(a) 2-ethyl-9 α -fluoro-11 β ,17 α ,20 β ,21-tetrahydroxy-4-pregnen-3-one 20-benzoate, 21-acetate produces 2-ethyl-9 α -fluoro-17 α ,20 β ,21-trihydroxy-4-pregnen-3,11-dione 20-benzoate, 21-acetate.

(b) 2-methyl-9 α -fluoro-11 β ,17 α ,20 β ,21-tetrahydroxy-4-pregnen-3-one 20,21-dipropionate produces 2-methyl-9 α -fluoro-17 α ,20 β ,21-trihydroxy-4-pregnen-3,11-dione 20,21-dipropionate.

(c) 2-propyl-9 α -fluoro-11 β ,17 α ,20 β ,21-tetrahydroxy-4-pregnen-3-one 20-butylate, 21-acetate produces 2-propyl-9 α -fluoro-17 α ,20 β ,21-trihydroxy-4-pregnen-3,11-dione 20,21-dipropionate.

(d) 2-benzyl-9 α -fluoro-11 β ,17 α ,20 β ,21-tetrahydroxy-4-pregnen-3-one 20-valerate, 21-acetate produces 2-benzyl-9 α -fluoro-17 α ,20 β ,21-trihydroxy-4-pregnen-3,11-dione 20,21-dipropionate.

(e) 2-butyl-9 α -fluoro-11 β ,17 α ,20 β ,21-tetrahydroxy-4-pregnen-3-one 20,21-dipropionate produces 2-butyl-9 α -fluoro-17 α ,20 β ,21-trihydroxy-4-pregnen-3,11-dione 20,21-dipropionate.

(f) 2-hexyl-9 α -fluoro-11 β ,17 α ,20 β ,21-tetrahydroxy-4-pregnen-3-one 20,21-diphenylpropionate produces 2-hexyl-9 α -fluoro-17 α ,20 β ,21-trihydroxy-4-pregnen-3,11-dione 20,21-diphenylpropionate.

(g) 2-octyl-9 α -fluoro-11 β ,17 α ,20 β ,21-tetrahydroxy-4-pregnen-3-one 20,21-dihexanoate produces 2-octyl-9 α -fluoro-11 β ,17 α ,20 β ,21-tetrahydroxy-4-pregnen-3,11-dione 20,21-dihexanoate.

fluoro-17 α ,20 β ,21-trihydroxy-4-pregnene-3,11-dione 20,21-dihexanoate.

In the same manner as shown in Examples 32 and 33 oxidation of 2-lower-alkyl-9 α -fluoro-11 β ,17 α ,20 β ,21-tetrahydroxy-4-pregnene-3-one 20,21-diacylate wherein the lower-alkyl has from one to eight carbon atoms and the acyl of the acylate of the esters is of a hydrocarbon carboxylic acid containing from one to eight carbon atoms, inclusive, produces the other corresponding 2-lower-alkyl-9 α -fluoro-17 α ,20 β ,21-trihydroxy-4-pregnene-3,11-dione 20,21-diacylates.

EXAMPLE 35

2-methyl-9 α -fluoro-17 α ,20 β ,21-trihydroxy-4-pregnene-3,11-dione

In the same manner as shown in Example 14 2-methyl-9 α -fluoro-17 α ,20 β ,21-trihydroxy-4-pregnene-3,11-dione 20,21-diacetate was hydrolyzed in a nitrogen atmosphere with an aqueous alcoholic potassium carbonate solution to give 2-methyl-9 α -fluoro-17 α ,20 β ,21-trihydroxy-4-pregnene-3,11-dione.

EXAMPLE 36

2-methyl-9 α -fluoro-17 α ,20 β ,21-trihydroxy-4-pregnene-3,11-dione 21-trimethylacetate

A mixture of 0.5 gram of 2-methyl-9 α -fluoro-17 α ,20 β ,21-trihydroxy-4-pregnene-3,11-dione, five milliliters of pyridine and one milliliter of trimethylacetyl chloride was allowed to stand at room temperature for a period of eighteen hours. Thereafter the mixture was poured into fifty milliliters of cold water and the reaction mixture extracted with two 25-milliliter portions of methylene chloride. Methylene chloride extracts were washed with water, dried over anhydrous sodium sulfate and evaporated and the thus produced residue was recrystallized from ethyl acetate-Skellysolve B hexanes to give pure 2-methyl-9 α -fluoro-17 α ,20 β ,21-trihydroxy-4-pregnene-3,11-dione 21-trimethylacetate.

In the same manner as shown in Example 35 other selectively esterified 2-lower-alkyl-9 α -fluoro-17 α ,20 β ,21-tetrahydroxy-4-pregnene-3,11-dione 21-acylates are prepared by reacting the corresponding 2-lower-alkyl-9 α -fluoro-17 α ,20 β ,21-trihydroxy-4-pregnene-3,11-dione with a halide of a sterically hindered acid such as the chlorides and bromides of trimethylacetic acid, triethylacetic acid, diisopentylacetic acid or the like.

EXAMPLE 37

2-methyl-9 α -fluorohydrocortisone 21-trimethylacetate

One gram of 2-methyl-9 α -fluoro-11 β ,17 α ,20 β ,21-tetrahydroxy-4-pregnene-3-one 21-trimethylacetate (Example 32) was stirred for a period of 96 hours at room temperature (about 22 to 25 degrees centigrade) with one gram of manganese dioxide freshly prepared in the manner shown by Attenburrow et al., Journ. Chem. Soc., 1094 (1952) in 75 milliliters of methylene dichloride. The mixture was then filtered to remove the manganese dioxide. The precipitated manganese dioxide was washed with methylene dichloride and the washings and methylene dichloride filtrate combined, dried and evaporated to give a residue which was recrystallized from acetone and Skellysolve B hexanes to give pure 2-methyl-9 α -fluoro-11 β ,17 α ,21-trihydroxy-4-pregnene-3,20-dione 21-trimethylacetate (2-methyl-9 α -fluorohydrocortisone trimethylacetate).

In the same manner as shown in Example 37 the 2-methyl-9 α -fluorohydrocortisone 21-trimethylacetate is hydrolyzed with potassium carbonate in ethanol solution in a nitrogen atmosphere to give the free alcohol 2-methyl-9 α -fluoro-11 β ,17 α ,21-trihydroxy-4-pregnene-3,20-dione (2-methyl-9 α -fluorohydrocortisone) possessing several times the glucocorticoid activity of the parent compound, hydrocortisone.

Treating the solution of 2-methyl-9 α -fluorohydrocortisone in pyridine with an acyl halide or acid anhydride of

an organic carboxylic acid preferably of a hydrocarbon carboxylic acid is productive of esters of 2-methyl-9 α -fluorohydrocortisone such as illustratively the acetate, the propionate, the butyrate, the valerate, the hexanoate, the 5 benzoate, the phenylacetate, the phenyl propionate, the 2-furoate, the β -cyclopentylpropionate or the like.

EXAMPLE 38

2-methyl-9 α -fluoro cortisone 21-trimethylacetate

10 In the same manner as shown in Example 37 oxidizing with freshly precipitated manganese dioxide in methylene dichloride solution 2-methyl-9 α -fluoro-17 α ,20 β ,21-tetrahydroxy-4-pregnene-3,11-dione 21-trimethylacetate yielded the 2-methyl-9 α -fluoro-17 α ,20 β ,21-trihydroxy-4-pregnene-3,11,20-trione (2-methyl-9 α -fluoro cortisone) 21-trimethylacetate.

In the same manner as shown in Examples 37 and 38 oxidizing 2-lower-alkyl-9 α -fluoro-11 β ,17 α ,20 β ,21-tetrahydroxy-4-pregnene-3-one or 2-lower-alkyl-9 α -fluoro-17 α ,20 β ,21-trihydroxy-4-pregnene-3,11-dione 21-acylates wherein the lower-alkyl group has from one to eight carbon atoms and the 21-acyloxy group is of a hydrocarbon carboxylic acid containing from one to eight carbon atoms, inclusive, with manganese dioxide in a

25 non-oxidizable solvent such as methylene chloride, chloroform, carbon tetrachloride, hexanes, heptanes or the like, produces the corresponding 2-lower-alkyl-9 α -fluorohydrocortisone 21-ester respectively the 2-lower-alkyl-9 α -fluoro cortisone 21-ester.

30 Through hydrolysis performed in Example 14 and subsequent reesterification other esters of 2-lower-alkyl-9 α -fluorohydrocortisone and 2-lower-alkyl-9 α -fluoro cortisone can be produced. Vigorous esterification procedures at high temperatures, above seventy degrees centigrade, give the acylates of 2-methyl-9 α -fluorohydrocortisone wherein the 11 β , the 17 α , and the 21-position are esterified. Vigorous conditions used on 2-lower-alkyl-9 α -fluoro cortisone produces the diester that is 2-lower-alkyl-9 α -fluoro cortisone 17 α ,21-diacylate, which are active adrenocortical hormones with prolonged action.

40 It is to be understood that the invention is not to be limited to the exact details of operation or exact compounds shown and described as obvious modifications and equivalents will be apparent to one skilled in the art, and 45 the invention is therefore to be limited only by the scope of the appended claims.

We claim:

1. 2-methyl-17 α ,20 β ,21-trihydroxy-4-pregnene-3,11-dione.
2. 2-methyl-11 β ,17 α ,20 β ,21-tetrahydroxy-4-pregnene-3-one.
3. 2-methyl-9 β ,11 β -epoxy-17 α ,20 β ,21-trihydroxy-4-pregnene-3-one 20,21-diacetate.
4. 2-methyl-9 α -fluoro-11 β ,17 α ,20 β ,21-tetrahydroxy-4-pregnene-3-one.
5. 2-methyl-9 α -fluoro-11 β ,17 α ,20 β ,21-tetrahydroxy-4-pregnene-3-one 20,21-diacylate.
6. 2-methyl-9 α -fluoro-17 α ,20 β ,21-trihydroxy-4-pregnene-3,11-dione.
7. A process for the production of a 2-lower-alkyl-9 α -fluoro-11 β ,17 α ,20,21-tetrahydroxy-4-pregnene-3-one which comprises the following steps: (1) treating a 11 β -hydroxy-21-acyloxy-4,17(20)-[trans]-pregnadien-3-one wherein the acyloxy group is of an organic carboxylic acid containing from one to eight carbon atoms with a lower-alkyl ester of oxalic acid in the presence of an alkali metal base to give the corresponding alkali-metal enolate of 2-lower-alkyloxyoxalyl-11 β -hydroxy-21-acyloxy-4,17(20)-[trans]-pregnadien-3-one 65 wherein the alkyl group contains from one to eight carbon atoms and the alkali metal has an atomic weight between six and forty; (2) treating the thus produced alkali-metal enolate of 2-lower-alkyloxyoxalyl-11 β -hydroxy-21-acyloxy-4,17(20)-[trans]-pregnadien-3-one with

a lower-alkyl halide, wherein alkyl is defined as before, and the halogen is of atomic weight between 34 and 130, to give the corresponding 2-lower-alkyloxyoxalyl-2-lower-alkyl - 11 β - hydroxy - 21 - acyloxy - 4,17(20) - [trans]-pregnadien-3-one; (3) hydrolyzing the 2-lower-alkyloxyoxalyl - 2 - lower - alkyl - 11 β - hydroxy - 21 - acyloxy - 4,17(20) - [trans]-pregnadien - 3 - one with an alkali alkoxide wherein alkali is defined as before and wherein the alkyl group of the alkoxy group is defined as before to give the corresponding 2-lower-alkyl-11 β ,21-dihydroxy-4,17(20) - [trans]-pregnadien - 3 - one; (4) treating the thus produced 2 - lower - alkyl - 11 β ,21 - dihydroxy - 4,17(20) - [trans]-pregnadien - 3 - one with an esterifying agent selected from halides and anhydrides of organic carboxylic acids containing from one to eight carbon atoms, inclusive, to obtain the corresponding 2-lower - alkyl - 11 β - hydroxy - 21 - acyloxy - 4,17(20) - [trans]-pregnadien-3-one; (5) treating the thus obtained 2 - lower - alkyl - 11 β - hydroxy - 21 - acyloxy - 4,17(20) - [trans]-pregnadien-3-one with osmium tetroxide in tertiary butyl alcohol in the presence of pyridine to obtain an intermediate 17(20)-osmate which is decomposed with aqueous sulfuric acid to give a 2 - lower - alkyl-11 β ,17 α ,20 β - trihydroxy - 21 - acyloxy - 4 - pregnen - 3 - one; (6) esterifying the thus produced 2-lower-alkyl-11 β ,17 α ,20 β - trihydroxy - 21 - acyloxy - 4 - pregnen - 3 - one with an acylating agent selected from halides and anhydrides of organic carboxylic acids containing from one to eight carbon atoms, inclusive, to give a 2-lower-alkyl - 11 β ,17 α - dihydroxy - 20 β ,21 - diacyloxy - 4 - pregnen-3-one; (7) treating the thus produced 2-lower-alkyl-11 β ,17 α - dihydroxy - 20 β ,21 - diacyloxy - 4 - pregnen - 3 - one with an N-halo compound selected from the group consisting of N-haloamide and N-haloimide, and treating the thus obtained product with anhydrous sulfur dioxide to produce the 2 - lower - alkyl - 17 α - hydroxy-20 β ,21-diacyloxy - 4,9(11) - pregnadien - 3 - one; (8) treating the thus produced 2-lower-alkyl-17 α -hydroxy-20 β ,21-diacyloxy - 4,9(11) - pregnadien - 3 - one with a hypohalous acid in which the halogen atom has an atomic weight between 34 and 130 to give the corresponding 2-lower - alkyl - 9 α - halo - 11 β ,17 α - dihydroxy - 20 β ,21-diacyloxy-4-pregn-3-one; (9) treating the thus produced 2 - lower - alkyl - 9 α - halo - 11 β ,17 α - dihydroxy - 20 β ,21-diacyloxy-4-pregn-3-one with anhydrous alkali acetate wherein alkali is defined as hereinbefore in a substantially water-free solvent to yield 2 - methyl-9 β ,11 β -epoxy-17 α -hydroxy-20 β ,21-diacyloxy-4-pregn-3-one; (10) treating the thus produced 2 - lower - alkyl - 9 β ,11 β - epoxy - 17 α - hydroxy-20 β ,21-diacyloxy - 4 - pregnen - 3 - one; (10) treating the thus produced 2 - lower - alkyl - 9 β ,11 β - epoxy - 17 α - hydroxy - 20 β ,21 - diacyloxy - 4 - pregnen - 3 - one with hydrogen fluoride in the presence of a strong acid to give the corresponding 2-lower-alkyl-9 α -fluoro-11 β ,17 α -dihydroxy - 20 β ,21 - diacyloxy - 4 - pregnen - 3 - one; and (11) hydrolyzing in an alkali medium the thus produced 2 - lower - alkyl - 9 α - fluoro - 11 β ,17 α - dihydroxy-20 β ,21 diacyloxy - 4 - pregnen - 3 - one to obtain the corresponding 2 - lower - alkyl - 9 α - fluoro - 11 β ,17 α ,20 β ,21-tetrahydroxy-4-pregn-3-one.

8. A process for the production of 2-methyl-9 α -fluoro-11 β ,17 α ,20 β ,21-tetrahydroxy-4-pregn-3-one which comprises the following steps: (1) treating a 11 β -hydroxy-21-acetoxy-4,17(20)-[trans]-pregnadien-3-one with a lower-alkyl ester of oxalic acid in the presence of an alkali metal alkoxide to give the corresponding 2-lower-alkyloxyoxalyl-11 β - hydroxy - 21 - acetoxy - 4,17(20) - [trans]-pregnadien-3-one wherein the alkyl group contains from one to eight carbon atoms and the alkali metal has an atomic weight between six and forty; (2) treating the thus produced alkali-metal enolate of 2-lower-alkyloxyoxalyl-11 β - hydroxy - 21 - acetoxy - 4,17(20) - [trans]-pregnadien-3-one with a methyl halide wherein the halogen is of atomic weight between 34 and 130, to give the corresponding 2-lower-alkyloxyoxalyl-2-methyl-11 β -hydroxy-21-acetoxy-4,17(20)-[trans]-pregnadien-3-one; (3) hydrolyzing

the 2-lower-alkyloxyoxalyl-2-methyl-11 β -hydroxy-21-acetoxy-4,17(20)-[trans]-pregnadien-3-one with an alkali alkoxide wherein alkali is defined as before and wherein the alkyl group of the alkoxy group is defined as before to give 2-methyl-11 β ,21-dihydroxy-4,17(20)-[trans]-pregnadien-3-one; (4) treating the thus produced 2-methyl-11 β ,21 - dihydroxy - 4,17(20) - [trans] - pregnadien - 3 - one with acetic anhydride to obtain the 2-methyl-11 β -hydroxy - 21 - acetoxy - 4,17(20) - [trans] - pregnadien - 3 - one; (5) treating the thus obtained 2-methyl-11 β -hydroxy - 21 - acetoxy - 4,17(20) - [trans] - pregnadien - 3 - one with osmium tetroxide in tertiary butyl alcohol in the presence of pyridine to obtain an intermediate 17(20)-osmate which is decomposed with aqueous sulfuric acid to give 2-methyl-11 β ,17 α ,20 β -trihydroxy-21-acetoxy-4-pregn-3-one; (6) treating the thus produced 2-methyl-11 β ,17 α ,20 β - trihydroxy - 21 - acetoxy - 4 - pregnen - 3 - one with acetic anhydride to obtain 2-methyl-11 β ,17 α -dihydroxy-20 β ,21-diacyloxy-4-pregn-3-one; (7) treating the thus produced 2-methyl-11 β ,17 α -dihydroxy-20 β ,21-diacyloxy-4-pregn-3-one with N-halo compound selected from the group consisting of N-haloamides and N-haloimides and treating the thus obtained product with anhydrous sulfur dioxide to produce the 2-methyl-17 α -hydroxy - 20 β ,21 - diacyloxy-4,9(11)-pregnadien-3-one; (8) treating the thus produced 2-methyl-17 α -hydroxy-20 β ,21-diacyloxy-4,9(11)-pregnadien-3-one with a hypohalous acid in which the halogen atom has an atomic weight between 34 and 130 to give the corresponding 2-methyl-9 α -halo - 11 β ,17 α - dihydroxy - 20 β ,21 - diacyloxy-4,9(11)-pregnadien-3-one; (9) treating the thus produced 2 - lower - alkyl - 9 α - halo - 11 β ,17 α - dihydroxy - 20 β ,21-diacyloxy-4-pregn-3-one with anhydrous alkali acetate wherein alkali is defined as hereinbefore in a substantially water-free solvent to yield 2 - methyl-9 β ,11 β -epoxy-17 α -hydroxy-20 β ,21-diacyloxy-4-pregn-3-one; (10) treating the thus produced 2 - lower - alkyl - 9 β ,11 β - epoxy - 17 α - hydroxy-20 β ,21-diacyloxy-4-pregn-3-one with hydrogen fluoride in the presence of a strong acid to give 2-methyl-9 α -fluoro-11 β ,17 α -dihydroxy-20 β ,21-diacyloxy-4-pregn-3-one, and (11) hydrolyzing in an alkali medium the thus produced 2-methyl-9 α -fluoro-11 β ,17 α ,20 β ,21-tetrahydroxy-4-pregn-3-one.

9. A compound selected from the group consisting of 2 - lower - alkyl - 11 β ,17 α ,20 β - trihydroxy - 21 - acyloxy-4-pregn-3-one, 2-lower-alkyl-11 β ,17 α -dihydroxy-20 β ,21-diacycloxy-4-pregn-3-one, and 2-lower-alkyl-11 β ,17 α ,20 β ,21-tetrahydroxy-4-pregn-3-one, wherein the lower alkyl radical contains from one to eight carbon atoms, inclusive, and wherein the acyl group of acyloxy is of a hydrocarbon carboxylic acid containing from one to eight carbon atoms, inclusive.

10. A compound selected from the group consisting of 2 - lower - alkyl-17 α -hydroxy-20 β ,21-diacyloxy-4-pregnene-3,11-dione and 2-lower-alkyl-17 α ,20 β ,21-trihydroxy-4-pregnene-3,11-dione, wherein the lower-alkyl radical contains from one to eight carbon atoms, inclusive, and wherein the acyl group of acyloxy is of a hydrocarbon carboxylic acid containing from one to eight carbon atoms, inclusive.

11. A compound selected from the group consisting of 2 - lower - alkyl - 17 α - hydroxy - 20 β ,21 - diacyloxy-4,9(11)-pregnadien-3-one and 2-lower-alkyl-17 α ,20 β ,21-trihydroxy-4,9(11)-pregnadien-3-one, wherein the lower-alkyl radical contains from one to eight carbon atoms, inclusive, and wherein the acyl group of acyloxy is of a hydrocarbon carboxylic acid containing from one to eight carbon atoms, inclusive.

12. A compound selected from the group consisting of 2 - lower - alkyl - 9 α - halo - 11 β ,17 α - dihydroxy - 20 β ,21-diacycloxy-4-pregn-3-one, 2-lower-alkyl-9 α -halo-11 β ,17 α ,20 β ,21-trihydroxy - 21 - trimethylacetoxy - 4 - pregnen-3-one, and 2-lower-alkyl-9 α -halo-11 β ,17 α ,20 β ,21-tetrahydroxy-4-pregn-3-one, wherein the lower-alkyl radical contains from one to eight carbon atoms, inclusive, where-

in the acyl group of acyloxy is of a hydrocarbon carboxylic acid containing from one to eight carbon atoms, inclusive, and wherein the halo atoms are of atomic weight seventeen through 130.

13. 2 - lower - alkyl - $9\beta,11\beta$ - epoxy - 17α - hydroxy- $20\beta,21$ -diacyloxy-4-pregn-3-one, wherein the acyl group of acyloxy is of a hydrocarbon carboxylic acid containing from one to eight carbon atoms, inclusive, and wherein the lower-alkyl radical contains from one to eight carbon atoms, inclusive.

14. A compound selected from the group consisting of 2 - lower - alkyl - 9α - halo - 17α - hydroxy - $20\beta,21$ - diacyloxy - 4 - pregnene-3,11-dione, 2-lower-alkyl- 9α -halo- $17\alpha,20\beta$ - dihydroxy - 21 - trimethylacetoxy - 4 - pregnene-3,11-dione, and 2-lower-alkyl- 9α -halo- $17\alpha,20\beta,21$ -trihydroxy-4-pregnene-3,11-dione, wherein the lower-alkyl radical contains from one to eight carbon atoms, inclusive,

wherein the acyl group of acyloxy is of a hydrocarbon carboxylic acid containing from one to eight carbon atoms, inclusive, and wherein the halo atoms are of atomic weight seventeen through 130.

UNITED STATES PATENT OFFICE
Certificate of Correction

Patent No. 2,852,538

September 16, 1958

Mary A. Scheri et al.

It is hereby certified that error appears in the printed specification of the above numbered patent requiring correction and that the said Letters Patent should read as corrected below.

Columns 3 and 4, Formula X should appear as shown below instead of as in the patent:

column 4, line 56, for "pregness" read —pregnenes—; line 60, for "alkyloxyalyl" read —alkyloxyoxalyl—; column 6, line 68, for "triphenylmethyl" read —triphenylmethyl—; column 9, line 55, for "thiry" read —thirty—; column 12, line 35, for "are produce" read —are produced—; column 14, line 45, for "idodie" read —iodide—; column 16, lines 28 and 29, for "-11, β 21—" read —-11 β ,21—; column 22, line 71, for "21-triethylacetate" read —21-trimethylacetate—; column 30, line 61, for "-11 β ,17 α ,20,21—" read —-11 β ,17 α ,20 β ,21—; column 31, line 19, for "acyolxy" read —acyloxy—; line 24, for "-17 β ,17 α ,20 β —" read —11 β ,17 α ,20 β —; column 32 lines 47 and 71, for "diacycloxy", each occurrence, read —diacyloxy—.

Signed and sealed this 14th day of July 1959.
